UNITED STATES PATENT OFFICE.

ARTHUR BESSEY SMITH, OF EVANSTON, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MULTIOFFICE AUTOMATIC TELEPHONE SYSTEM.

Application filed May 8, 1922, Serial No. 559,337. Renewed September 7, 1926.

The present invention relates in general to multi-office automatic telephone systems, but as to some of its features, is concerned more particularly with systems of the above 5 named character in which the inter-office trunking is arranged so as to group the offices into a number of separate networks or geographical districts. In certain respects this 10 case may be considered as an improvement on my prior application, Serial No. 550,451, filed April 7, 1922.

One object is the provision of new and improved trunking arrangements and improved 15 cooperating equipment for multi-office telephone systems, whereby a call may be tentatively trunked to a plurality of districts, each of which contains offices having the first characters similar to offices in the other districts, and whereby the call may be routed 20 subsequently to the right office in the proper district.

Another object has to do with the circuit 25 details of the various so called universal switches which are employed to carry out the principles of the invention.

Still another object is the production of a new and improved method for combining 30 two comparatively small groups of trunks into one larger and more efficient group and for separating the two groups at a point where they diverge.

Still another object is the production of a new impulse relaying repeater which repeats all the impulses after the first series 35 but does not repeat the first series of impulses.

The above pointed out objects, together 40 with others not specifically mentioned at this time, will be explained fully hereinafter, reference being had to the accompanying drawings, comprising Figs. 1-12, inclusive.

Referring now to the drawings, Figs. 1-8, inclusive, show by means of the usual circuit diagrams a sufficient amount of the apparatus 45 in a system embodying the principles of the invention to enable the same to be understood; Fig. 9 shows the front part of the calling device, or dial as it is commonly called, with which each subscriber's telephone is equipped; Fig. 10 is a map showing the location of the various offices of the system disclosed; Fig. 11 is a trunking diagram showing how calls are trunked from one of the offices to every other office in the

system; and Fig. 12 is a layout showing how 55 the sheets of drawings including Figs. 1-8, inclusive, are joined together.

Of the equipment shown in Figs. 1-8, inclusive, the equipment shown in Figs. 1-4, inclusive, is assumed to be in Lincoln, Figs. 10 and 11; the equipment shown in Figs. 5 and 6 is assumed to be in Medbury; the equipment shown in Fig. 7 in Pontiac; and the equipment shown in Fig. 8 in Market.

Referring now particularly to Figs. 1-8, inclusive, and Fig. 11, the automatic substations A and A', Fig. 11, of which the circuits are shown in Figs. 1 and 8, respectively, are identical with each other, and are of the usual automatic type, having talking, signalling, and switch controlling instrumentalities.

The line switches C and C', Fig. 11, in which the lines of substations A and A', respectively, terminate as shown in Figs. 1 and 8, are also identical with each other, and are of the well known rotary type in which the wipers have no normal position and move in a forward direction only.

The selectors D, E-E², inclusive, F-F², inclusive, G-G⁵, inclusive, and H, Fig. 11, of which the selectors D, G', G², E', F', G³, G⁵ and H are shown in Figs. 1, 4-6, inclusive, 7, and 8, are mechanically of the well known vertical and rotary type and accordingly 85 their bank contacts are arranged in horizontal rows or levels. The circuits of these selectors are all identical with each other, with the usual exception that, whereas those which are associated with trunks from distant 90 offices do not have release trunk conductors carried back with the talking conductors, the selectors which receive traffic from local switches do. The circuits of the selectors G' and E', which are a local selector and an incoming selector, respectively, are shown 95 complete in Figs. 4 and 5, respectively, and will be described fully hereinafter.

The connector J, Figs. 8 and 11, is mechanically identical with the selectors. Its 100 circuits, however, differ from those of a selector, and are shown in full in Fig. 8.

The secondary switches SS-SS²⁷, inclusive, Fig. 11, of which the switches SS², SS⁵, SS⁷-SS¹⁰, inclusive, SS¹⁶-SS¹⁹, inclusive, and 105 SS²⁴-SS²⁶, inclusive, are shown in Figs. 2-7, inclusive, are mechanically identical with each other and with the rotary line switches

C and C', hereinbefore described. The circuits of all secondary switches are identical with each other, with the exception of the secondary switch SS¹⁷, Figs. 6 and 11, and 5 are changed only slightly from the circuits of the primary line switches C and C'. The slight change is necessary in some instances in order to prevent the switching relay of one of these switches from energizing immediately upon the switch being seized, owing 10 to ground being placed upon the release trunk conductor thereof when the switch is seized. However, barring the previously mentioned secondary switch SS¹⁷, the circuits of all the secondary switches are made 15 alike in order to permit the switches themselves to be interchanged when necessary. The circuits of the secondary switch SS¹⁷ are identical with the circuits of any of the other secondary switches, with the exception 20 of an added pair of contacts on the switching relay thereof and an added wiper, the functions of which will be described.

Regarding the universal switchers US-US⁴, 25 inclusive, Fig. 11, of which the universal switchers US', US⁴ and US⁸ are shown in Figs. 1-3, inclusive, respectively, each comprises the necessary relays and a controlling switch. Each of these controlling switches 30 is of simple construction. The controlling switch associated with the universal switcher US', Fig. 1, for example, comprises a stepping magnet 80, wiper 82 and associated back contacts, release magnet 81, and off 35 normal contacts 79. The wiper 82 is moved step by step in one plane by stepping magnet 80, and is subsequently restored to normal by release magnet 81. Off normal contacts 79 are normally open, as shown, and 40 close upon wiper 82 being moved from its normal position. The circuits of the universal switchers US-US⁴, inclusive, while fundamentally similar to each other, differ somewhat from each other in circuit detail, 45 depending upon the situation in which they are used. The switchers US', US⁸, and US⁴ which are shown in Figs. 1, 3, and 2, respectively, are chosen as being typical ones. The circuits of these switchers will be 50 explained fully hereinafter.

The repeaters R-R¹³, inclusive, Fig. 11, are repeaters of the usual automatic type and each is provided with a repeating coil and the necessary relays as may be seen in 55 Figs. 2, 3, 4, 6, and 7, in which the circuit of the repeaters R-R⁴, inclusive, R⁸, and R¹³ are shown in detail.

The digit absorbing repeaters DAR-DAR², 60 inclusive, Fig. 11, of which the digit absorbing repeater DAR² is shown in full in Fig. 5, are similar to the repeaters R, R', etc., with the exception that each of the former is arranged so as to absorb the first digit or train of impulses delivered to it after 65 it is seized. The following impulses, how-

ever, are repeated in the usual manner to the distant office.

The bi-level repeater BLR Figs. 11 and 6, is an ordinary repeater so far as its repeating functions are concerned. This repeater 70 has an added relay which, together with cooperating circuits, enables an impulse of current to be sent over one side of the trunk momentarily when the repeater is seized from one path but not when the repeater is 75 seized from the other path. This repeater repeats impulses over the associated trunk in the usual manner after having been seized.

The traffic separator TS, Figs. 11 and 7, is connected with the opposite end of the 80 trunk to which the bi-level repeater BLR is connected. This traffic separator has suitable relays and cooperating circuits to enable it to choose one or the other of the outgoing paths, depending upon whether or not the 85 upper trunk conductor leading to it is grounded momentarily when the bi-level repeater BLR is seized.

Referring now particularly to Fig. 9, the exposed part of the calling device shown 90 therein is provided, not only with the digits 1 to 0, but also with the letters of the alphabet as shown. It will be noted that the letters of the alphabet are placed in order in the holes of the calling device from the 95 first to the tenth with the exception that the letter I, which is often mistaken for the digit 1, is placed in the first hole, and the letter O, which resembles the digit 0, is placed in the tenth hole of the calling device. 100 These two exceptions are made so that no harm results when a subscriber mistakes the letter I for the digit 1 or the letter O for the digit 0. In the directory, each subscriber's number comprises the first three 105 letters of the office name and four digits, for example MARKet-1234. The first three letters M, A, and R, or the ones to be dialed, are capitalized, so as to enable the subscriber to see at a glance which letters he must use 110 when calling a number.

Referring now particularly to Fig. 10, which, as before stated, is a map showing the approximate relative location of the offices in the present system, and also the 115 names of the various offices, the offices shown therein are divided into four groups which will be hereinafter called districts. This drawing shows also the trunking which is used to extend calls from Lincoln to each 120 of the other offices, giving an idea as to the manner in which the calls are distributed. Each of the trunks shown, of course, is only one of a group, there being a sufficient number to handle the traffic. It may be stated 125 that there are direct trunks (of which only a few are shown) from each office to every other office in the same district, thus weaving the offices in each district together into an integral network. The scheme used for 130

inter-district trunking in the present instance is to provide direct trunks from the originating office to the nearest or one of the nearest offices in the district for which 5 the call is intended, which office then takes on the character of a switching center. After a call has been trunked into a distant switching center, it is completed to the desired office over the regular inter-office net- 10 work local to the district. For example, on a call from Lincoln to Maburn, the call is trunked first to Dunham and then to Maburn, the trunk from Dunham to Maburn being used, not only in completing local calls 15 from Dunham to Maburn, but also in completing inter-district calls.

The names of the various offices shown are assumed to have belonged to these offices since manual equipment was first installed and it 20 is assumed further that a change of office names, when the system was changed from manual to automatic, was undesirable and was not made. That being the case, special 25 trunking arrangements are necessitated in order to enable a number of offices to be reached by way of a common switching center without making it necessary for calls to be trunked over such long and devious paths that the efficiency gained by providing 30 switching centers is lost on account of the intricate trunking network necessitated. For example, it will be noted that the first two letters M and A of Market, which office is located at the right hand end of the system, 35 are the same as the first two letters M and A of Maburn, which office is located at the extreme left hand of the systems. It is evident that, when a subscriber in Maburn or Market is being called, it cannot be definitely 40 determined until the third letter is dialed whether the call is intended for Maburn or for Market.

In order to meet these conditions, universal switchers have been placed in each office, 45 and when a subscriber dials a letter which does not determine definitely to which district the call is going, a universal switcher is seized, which switcher takes a trunk to each of the districts to which the call might go. 50 All the trunks, except the one that is actually needed to complete the call, are released by the universal switcher as soon as the subscriber has called enough of the number to determine which trunk will be used.

55 Since more than one letter is associated with each digit appearing on the face at the calling device used, the letters of two offices do not need to be the same in order to conflict with each other. In order to enable the 60 conflicting office names to be seen at a glance, the numerical equivalent of the first three letters in each office name is written underneath the name of the office, Fig. 10. For example, the numerical equivalent of the first 65 three letters of Polk is 605 and the numerical

equivalent of the first three letters of North is 607.

Referring now particularly to Fig. 11, which is a trunking diagram showing how the problems presented in Fig. 10 are solved, 70 the trunking will be explained more in detail. In order to do this, it will be assumed that the subscriber at substation A in Lincoln desires to call the subscriber at substation A' in Market. Upon the receiver being 75 removed at substation A, the individual line switch C picks out an idle first selector, the first selector D for example. In response to the calling of the first letter M in the desired number, the selector D raises its wipers 80 to the fifth level (the letter M appearing in the fifth hole of the calling device Fig. 9) and rotates them in search of an idle trunk. It will be assumed that the trunk extended to the universal switcher US' is the first one 85 found to be idle and consequently the one selected. When the trunk which extends to the universal switcher US' is seized, the said universal switcher US' connects up the secondary switch SS² and the secondary switch 90 SS⁵, but does not connect up the secondary switch SS^{2a} for the time being. The secondary switches SS² and SS⁵ operate to seize idle trunks, which trunks it will be assumed are the ones shown. That being the case, the selector E in Dunham and the selector E' in Medbury, are prepared for operation in the usual manner.

In response to the calling of the second letter A in the desired number, the selector E in Dunham and the selector E' in Medbury, which selectors are controlled by the repeaters R and R', respectively, raise their wipers to the first level and select idle trunks, the trunks extending to the selectors 100 F and F' for example, and in response to the calling of the third letter R in the desired number, the selectors F and F' raise their wipers to the seventh level and rotate them in search of idle trunks. The seventh 105 level of the selector F is dead, and consequently its trunk selecting operation is of no avail at this time. The selector F', upon rotating, selects an idle trunk in the seventh level, the trunk extending to the secondary switch SS¹⁷ for example. The secondary switch SS¹⁷, upon operating, selects an idle trunk, the one extending to the bi-level repeater BLR for example. The group of 110 trunks to which the trunk associated with the bi-level repeater BLR belongs performs the work of two groups of trunks. Each of these trunks is accessible from two paths, and, upon one of these trunks being seized, one or the other of the switches associated therewith in the distant office is connected up by a traffic separator such as the traffic separator TS, depending upon from which path the repeater is seized. In the present 115 case, since the repeater BLR is seized from 120

- the upper path, the second switch SS^{24} is connected up by the traffic separator TS. The switch SS^{24} , upon being connected up to the inter-office trunk, selects a trunk to the upper path, the second switch SS^{24} is connected up by the traffic separator TS. The switch SS^{24} , upon being connected up to the inter-office trunk, selects a trunk to the inter-office trunk, selects a trunk to the universal switcher US' to be the one selected, the secondary switches SS^2 and SS^5 are connected up in the usual manner.
- 5 Market, the trunk extending to the selector G^5 by way of the repeater R^{13} for example. In the universal switcher US', a recording device which has recorded the part of the number called, upon responding to the calling of the third letter R, disconnects the secondary switch SS^2 , whereupon the trunk to Dunham is freed, and cuts off its own line relay and does not respond to the calling of the remaining part of the number.
- 10 15 In response to the calling of the four digits in the desired number, the connection is extended to the desired line in the usual manner, by way of the selectors G^5 and H and the connector J.
- 20 Assuming now that the subscriber at substation A is calling a subscriber in Maburn, the call proceeds as in the previously described case upon the dialing of the first two letters M and A in the desired number.
- 25 Assuming that the call takes the same path as in the previous example and is extended to the selector F in Dunham and to the selector F' in Medbury, these two selectors F and F', are raised to the second level
- 30 upon the calling of the third letter B in the desired number. The second level of the selector F' is dead and, consequently, the trunk selecting operation of the said selector F' is of no avail at this time. The second
- 35 level of the selector F, however, is not dead, and consequently the said selector F, upon rotating, selects an idle secondary switch, the secondary switch SS^{14} for example, which secondary switch, upon operating, selects an idle repeater, the repeater R^6 for example. That being the case, the distant selector in Maburn associated with the repeater R^6 is prepared for operation in the usual manner.
- 40 45 The universal switcher US', upon recording the third letter B in the desired number, cuts off the secondary switch SS^5 , whereupon the connection to Medbury is released in the usual manner.
- 50 In response to the calling of the four digits in the desired number, the connection is extended to the desired line in Maburn by means of the usual automatic switches such as are shown in Market.
- 55 Assuming now that the subscriber at substation A desires to call another subscriber whose line terminates in the same office as the line of substation A, the line switch C operates to extend the connection to the selector D in the usual manner when the receiver is removed at the calling substation. Upon the calling of the first letter L in the desired number, the selector D raises its wipers to the fifth level and rotates them
- 60 65 in search of an idle trunk. Assuming the trunk extending to the universal switcher US' to be the one selected, the secondary switches SS^2 and SS^5 are connected up in the usual manner.
- In response to the calling of the second letter I in the office name, the selectors in Dunham and Medbury to which the connection has been extended, the selectors E and E' for example, raise their wipers to the first level and select idle trunks, which trunks it will be assumed are the ones extending to the selectors F and F'.
- In response to the calling of the third letter N in the desired number, the selectors F and F' in Dunham and Medbury respectively, raise their wipers to the sixth level and rotate them in search of idle trunks. The trunk selecting operation of the selector F in Dunham is of no avail, the sixth level thereof being dead. The selector F' in Medbury, however, selects an idle secondary switch, the secondary switch S^{18} for example, and as a result the connection is extended by way of a bi-level repeater, the bi-level repeater BLR for example, traffic separator TS, and the secondary switch SS^{25} in Pontiac, to a thousands selector, the thousands selector G^8 for example.
- In the universal switcher US', the before mentioned recording device, upon recording the third letter dialed, disconnects the secondary switches SS^2 and SS^5 , whereupon the connection to Dunham and the connection to Pontiac by way of Medbury are released in the usual manner. As another result of the recording device in the universal switcher US' operating in response to the third letter N, the secondary switch SS^{28} is connected up and, upon operating, selects an idle thousands selector, the thousands selector G^8 for example. In response to the calling of the four digits in the desired number, the connection is extended to the desired line by way of the thousands selector G^8 , and a hundreds selector and a connector (not shown).
- The universal switcher US' which through its associated secondary switches SS and SS^{11} has access to trunks to Attington and to Dunham, connects up the secondary switch SS immediately upon being seized, but in case the second and third letters of Atlantic are called, the secondary switch SS^{11} is not connected up at all. However, if the third letter also is T, the secondary switch SS is disconnected, whereupon the connection to Dunham is released. At the same time, the secondary switch SS^{11} is connected up, whereupon a trunk to Attington is seized.
- Similarly the universal switcher US', which through its secondary switch SS^{10} has access to direct trunks to Beverly and through its secondary switch SS^8 has access to Cedar by way of the switching center Blazon, connects up the secondary switch

- SS³ immediately upon being seized thereby seizing a trunk to Blazon. If the second and third letters of Cedar are called, the secondary switch SS¹⁰ is not connected up; 5 the trunk to Beverly is not seized; and the connection is extended to the desired subscriber in Cedar in the usual manner. However, if the second and third letters of Beverly are called, the trunk to Blazon is 10 released and the trunk to Beverly is seized, upon the calling of the third letter, and the connection is completed in the usual manner, upon the calling of the four digits in the desired number.
- 15 The universal switcher US³ connects up the associated secondary switch SS⁷ immediately upon being seized and if either the second letter A of Saxony or the second letter E of Seminole is called the universal switcher US³ does not record the next letter in the number, but cuts off its line relay since the calling of the second letter A or the second letter E determines definitely that the call is going to Saxony or to Seminole and 20 not to South. If the second letter called, after the universal switcher US³ is seized, is O instead of A or E, the secondary switch SS⁷ is cut off, but the secondary switch SS⁹ is not connected up unless the third letter 25 called is the third letter U of South.
- Still another situation arises in connection with offices North, Polk, and Pontiac. When the universal switcher US is seized, upon the calling of either the letter N or the letter P, it immediately connects up the secondary switches SS³ and SS⁶, thereby seizing trunks to Dunham and to Medbury, and, 30 upon the calling of the second letter O of either North, Polk, or Pontiac, the connection is extended to a second selector in Medbury, the selector F' for example. In Dunham, the connection is extended to a digit absorbing repeater by the operation of the selector E, for example, to the digit absorbing repeater DAR, by way of the secondary switch SS¹². This digit absorbing repeater, 35 upon being seized, closes a control circuit for the distant associated selector in North immediately in the usual manner. This repeater, however, is arranged so as not to repeat the first series of impulses to the associated selector. If the third letter called is N, the connection is extended to Pontiac by way of a path which, for example, includes the secondary switch SS¹⁸, bi-level repeater BLR, traffic separator TS, and the secondary switch SS²⁵, and extends to a thousands selector such as the selector G³. If the third letter called is L, the connection is extended 40 to North by way of a secondary switch and a repeater, such as SS¹⁹ and R⁸. In either of these two cases the connection to Dunham is released upon the calling of the third letter. However, if the third letter called is R, the connection to Medbury is released and

the digit absorbing repeater DAR in Dunham, upon absorbing the first digit repeated to it after it is seized, is made ready to repeat the following digits.

It will be understood that certain calls 70 may be completed that do not pass through any universal switcher. One example of such a call will now be given. Assuming that the subscriber at substation A desires to converse with a subscriber whose line terminates in Upland, and assuming that his line is extended to the selector D upon the removal of his receiver, the said selector D raises its wipers to the eighth level and selects an idle secondary switch, the secondary switch SS⁴ for example, upon the calling of the first letter U in the desired number. The secondary switch SS⁴, upon operating, 75 selects an idle repeater, the repeater R' for example. That being the case, the associated selector E' in Medbury is prepared 80 for operation.

Upon the calling of the second letter P in the desired number, the selector E' in Medbury raises its wipers to the sixth level and 90 selects an idle secondary switch, the secondary switch SS¹⁶ for example. The secondary switch SS¹⁶, upon operating, selects an idle digit absorbing repeater, the digit absorbing repeater DAR² for example, that being the case, the distant associated selector in Upland is prepared for operation in the usual manner.

Upon the calling of the third letter L in the desired number, five impulses are delivered to the repeater DAR², but, as hereinbefore described, the first series of impulses sent to the repeater after it has been seized are not repeated over the outgoing trunk. In response to this series of interruptions the 100 repeated DAR² is made ready to repeat the succeeding trains of impulses over the outgoing trunk. 105

In response to the calling of the four digits in the desired number, the connection is extended to the desired line in Upland in the usual manner.

It is thought that the foregoing is sufficient to give a general understanding of the system and, accordingly, a detailed description of the operation of the apparatus shown in Figs. 1-8, inclusive, will now be given.

Call from Lincoln office to Market office.

For this purpose it will be assumed that 120 the subscriber at substation A, Fig. 1, whose line terminates in Lincoln, Figs. 10 and 11, desires to converse with the subscriber at substation A', Fig. 8, whose line terminates in Market, Figs. 10 and 11, and whose number is Market 3456.

When the receiver is removed at substation A, a circuit is closed over line conductors 2 and 3 for line relay 6 of the line switch C. Line relay 6, upon energizing, 125 130

places ground upon private normal conductor 4, thereby making the calling line busy immediately to the connectors which have access to it. The placing of ground upon 5 private normal conductor 4 also closes a circuit for switching relay 5 and stepping magnet 7 in series. As a further result of the energization of line relay 6, it connects, at armature 11, test wiper 14 to the circuit 10 of switching relay 5 and stepping magnet 7 at a point between the two. The operation now depends upon whether the trunk upon which the wiper 13-15, inclusive, of the switch are standing is busy or idle. If it is 15 idle, switching relay 5 energizes immediately, but assuming it to be busy, there is a ground potential on the test contact thereof; switching relay 5 is short circuited; and stepping magnet 7, which interrupts its own circuit, is operated in the manner of a buzzer 20 to advance the switch wipers step by step in search of an idle trunk. Assuming that the trunk terminating in bank contacts 16-18, inclusive, is the first one to be found idle, 25 switching relay 5, being no longer short circuited after test wipers 14 arrives upon the ungrounded test contact 17, energizes in series with stepping magnet 7. Stepping magnet 7, however, does not energize at this 30 time on account of the high resistance of switching relay 5. Upon energizing, switching relay 5 opens the test circuit and prepares the holding circuit at armature 9; and at armatures 8 and 10 disconnects line 35 conductors 2 and 3 from the winding of line relay 6 and ground, respectively, and extends them by way of the working contacts of these armatures, wipers 13, and 15, bank contacts 16 and 18, and trunk conductors 19 40 and 21 to the upper and lower windings of the line relay (not shown) of the selector D, which selector is denoted by the dotted rectangle bearing that reference character. In response to the energization of the line relay 45 of the selector D, the switch D is prepared for operation and a ground potential is placed upon release trunk conductor 20, thereby establishing the usual holding circuit for switching relay 5 of the line switch 50 C, before the slow acting line relay 6 has had time to deenergize.

The calling subscriber now turns the dial of his calling device or sender S, the front part of which is shown in Fig. 9, in accordance with the first letter M in the name of the office in which the desired line terminates, thereby producing five interruptions in the circuit of the line relay (not shown) of the selector D. In response to these five interruptions being produced in its line relay, 60 the selector D raises its wipers 22-24, inclusive, to the fifth level and rotates them in search of an idle trunk. It will be assumed that the trunk comprising conductors 32-34, 65 inclusive, and extending to the universal

switcher US', is the one seized. That being the case, line relay 36, upon energizing over the calling subscriber's loop, closes a circuit for release relay 37 at armature 47. Release relay 37, upon energizing, prepares a locking 70 circuit for relays 40 and 41, at armature 49; prepares a circuit for stepping magnet 80 at armature 50; and at armature 48 places ground upon release trunk conductor 33, thereby establishing the usual holding circuit 75 for the line switch C and the selector D. As a further result of the energization of line relay 36, it closes at armature 46 a circuit for impulse relays 68 and 69 in multiple. These impulse relays, upon energizing, close 80 local bridges across the associated trunk conductors at armatures 76 and 77.

In response to the closing of the local bridge across conductors 91 and 93 by armature 76 of impulse relay 68, line relay 102 of 85 the secondary switch SS⁵, upon energizing, places ground upon release trunk conductor 92 at armature 111; closes a circuit for switching relay 101 and stepping magnet 103 in series at armature 110; and at armature 109 connects test wiper 113 to the circuit of switching relay 101 and stepping magnet 103 at a point between the two. The secondary switch SS⁵ now selects an idle 90 trunk in the same manner as described hereinbefore for the primary line switch C. Assuming that the trunk extending to the repeater R' is the first one found to be idle, switching relay 101, being no longer short circuited, energizes when test wiper 113 arrives upon bank contact 116; opens the test circuit and prepares the holding circuit at armature 107; places a shunt around armature 110 and its working contact at armature 106; and at armatures 105 and 108 disconnects conductors 91 and 93 from line relay 102 and from ground, respectively, and extends them by way of wipers 112 and 114, bank contacts 115 and 117, and conductors 118 and 120 to the upper and lower windings of line relay 126 of the repeater R'. Line relay 126, upon energizing, closes a circuit for release relay 127 at armature 128. Release relay 127, upon energizing, places 100 ground upon release trunk conductor 119 at armature 130, thereby establishing the usual holding circuit for switching relay 101 of the secondary switch SS⁵. As a further result of the energization of line relay 126, it places a bridge across the inter-office trunk 105 conductors 131 and 132 at armature 129, whereupon line relay 165 of the associated selector E', Fig. 5, in Medbury, Figs. 10 and 11, energizes and closes a circuit for release relay 166 at armature 176. Release relay 166, upon energizing, prepares a circuit for 110 switching relay 169 at armature 177, and at armature 178 opens a point in the circuit of release magnet 170 and prepares a circuit for vertical magnet 172. 115

Returning now to the universal switcher US', Fig. 1, as a result of the local bridge being placed across conductors 94 and 96 at armature 77 by impulse relay 69, the associated secondary switch SS² operates in the usual manner to select an idle repeater. In this case it will be assumed that the repeater R is the one selected. That being the case, the line relay of the said repeater, upon energizing, in addition to closing a circuit for the associated release relay, closes a bridge across the associated trunk conductors, whereupon the selector E in Dunham, Fig. 11, is prepared for operation in the usual manner.

Returning again to the universal switcher US', Fig. 1, it will be noted that no impulse relay is provided for the trunk conductors of the secondary switch SS², and consequently the said switch is not operated for the time being.

The calling subscriber now operates his calling device in accordance with the second letter A in the name of the desired office, thereby producing one interruption in the circuit of line relay 36 of the universal switcher US'. Upon deenergizing in response to this interruption produced in its circuit, line relay 36 opens the circuit of impulse relays 68 and 69 at armature 46, whereupon the interruption is relayed to the circuits controlled by these relays at armatures 76 and 77.

Relay 126 of the repeater R', upon responding to the impulse relayed to it by impulse relay 68, interrupts the circuit of line relay 165 of the selector E' momentarily. Line relay 165, upon deenergizing, closes a circuit for vertical magnet 172 as follows: From ground by way of the resting contact of armature 184 and said armature, armature 176 and its resting contact, armature 178 and its working contact, relay 167, and vertical magnet 172 to battery. By the operation of vertical magnet 172, which magnet receives one impulse at this time, the wipers 186-188, inclusive, are raised opposite the first level of bank contacts. Relay 167, which relay it may be pointed out is slow acting so as to cause it to hold up during a series of interruptions delivered to vertical magnet 172, is energized in series with vertical magnet 172 at this time, and at armature 179 closes a circuit for stepping relay 168 upon the closure of off normal contacts 175. Stepping relay 168, upon energizing, prepares a circuit for rotary magnet 173 at armature 181, and at armature 180 closes a locking circuit for itself. A fraction of a second after the termination of the vertical movement of the switch wipers, slow acting relay 167 deenergizes and completes the circuit of rotary magnet 173. Rotary magnet 173, upon energizing, advances the wipers 186-188, inclusive, into engagement with the first set of bank contacts

in the level opposite which they are raised, at the same time opening the circuit of stepping relay 168. Stepping relay 168, upon deenergizing, opens the circuit of rotary magnet 173 at armature 181. Rotary magnet 173, upon deenergizing, closes its interrupter contacts 174 again. From this point the operation depends upon whether the trunk terminating in the first set of contacts is busy or idle. If it is idle, switching relay 169 energizes immediately, but if it is busy, switching relay 169 is short circuited by the ground potential which is present upon the test contact thereof, and stepping relay 168 energizes again, whereupon rotary magnet 173 energizes also and the wipers are advanced into engagement with the next set of bank contacts. This alternate operation of stepping relay 168 and rotary magnet 173 continues until an idle trunk is reached. When an idle trunk is reached, which trunk it will be assumed is the one extending to the selector F', switching relay 169, being no longer short circuited, energizes in series with stepping relay 168. Stepping relay 168, however, does not energize at this time owing to the high resistance of switching relay 169. As a result of the energization of switching relay 169, it removes ground from armature 176 of line relay 165 at armature 184, thereby opening the circuit of the slow acting release relay 166; opens the test circuit and prepares the holding circuit at armature 183; and at armatures 182 and 185 disconnects the incoming trunk conductors 131 and 132 from the windings of line relay 165 and extends them by way of wipers 186 and 188, the bank contacts with which these wipers are in engagement, and the associated trunk conductors to the upper and lower windings of the line relay of the selector F'. The line and release relays (not shown) of the selector F' now energize and the latter prepares the switch for operation and places ground upon the associated release trunk conductor, thereby establishing the usual holding circuit for switching relay 169 of the selector E' before the slow acting release relay 166 has had time to deenergize.

In the repeater R, Fig. 4, the line relay thereof, upon deenergizing momentarily in response to the interruption relayed to it by armature 77 of impulse relay 69 of the universal switcher US', interrupts the circuit of the line relay of the distant associated selector E in Dunham, Fig. 11. When this occurs, the selector E operates in the usual manner to raise its wipers to the first level and rotate them in search of an idle trunk. In this case, it will be assumed that the trunk extending to the selector F is the first one found to be idle, and consequently the one seized.

In the universal switcher US', line relay 36, upon deenergizing momentarily in re-

sponse to the interruption produced in its circuit by the calling subscriber, in addition to opening the circuit of impulse relays 68 and 69 as hereinbefore pointed out, closes 5 the following circuit for stepping magnet 80: From ground by way of the resting contact of armature 45 and said armature, armature 47 and its resting contact, armature 50 and its working contact, relay 38, and 10 stepping magnet 80 to battery. By the operation of stepping magnet 80, which magnet receives one impulse at this time, wiper 82 is advanced into engagement with the first associated bank contact 84. Relay 30 15 is energized in series with vertical magnet 80 and maintains the circuit of release magnet 81 open after the closure of off normal contacts 79, which closure occurs as soon as wiper 82 is moved from its normal position. 20 After the end of the stepping movement, series relay 38, upon deenergizing, completes at armature 51 a circuit for release magnet 81 by way of off normal contacts 79. Release magnet 81, however, having a com- 25 paratively heavy armature, the retaining spring of which is stiffly adjusted, is not able to energize immediately. A branch of the circuit of release magnet 81 extends by way of armature 83 and its resting contact, 30 wiper 82, blank contact 84, armature 52 and its resting contact, relay 40, and relay 39 to battery. Relays 40 and 39 energize in series over this circuit. Relay 40, upon energizing, closes a locking circuit for itself and for 35 relay 39 at the lightly adjusted armature 54, and prepares circuits for seizing relays 65-67, inclusive, at armature 55-57, inclusive, respectively. Relay 39, upon energizing, opens its initial circuit and that of relay 40 at armature 52 and at armatures 53 40 disconnects relay 41. Release magnet 81 energizes, a fraction of a second after its circuit and that of relays 39 and 40 are closed and after sufficient time has been al- 45 lowed for relay 40 to close the previously described locking circuit, thereby disconnecting wiper 82 at armature 83 and allowing it to be restored to normal position, the circuit of release magnet 81 being opened at off nor- 50 mal contacts 79 when wiper 82 reaches normal position.

One result so far accomplished, by the calling of the first two letters in the desired number, is that the connection has been ex- 55 tended over two paths, one path extending to the selector F in Dunham by way of the selector E, and the other path extending to the selector F' in Medbury by way of selector E'. Another result accomplished is 60 that the universal switcher US' has recorded the second letter dialled and is in readiness to record the third letter dialled and to make a corresponding definite choice of the route to be used in completing the connection.

65 The subscriber at substation A now op- erates his calling device in accordance with the third letter R in the desired number, thereby producing seven interruptions in the circuit of line relay 36 of the universal switcher US'. These seven interruptions 70 are relayed by relays 68 and 69 to the selectors F and F', Fig. 11, by way of the repeaters R and R'. The selector F', Fig. 5, in response to the seven interruptions produced in the circuit of its line relay, raises 75 its wipers 198-200, inclusive, step by step until they come to rest opposite the seventh level of bank contacts, after which it rotates them in search of an idle trunk in the usual manner. Assuming the trunk terminating 80 in bank contacts 215-217, inclusive, comprising conductors 227-229, inclusive, and extending to the secondary switch SS¹⁷, to be the first one found to be idle and consequently the one selected, line relay 281 of 85 the switch SS¹⁷ is energized in response to the switch being seized. Upon energizing, line relay 281 closes the usual circuits, whereupon the switch wipers are advanced into engagement with an idle trunk in the usual 90 manner. It will be assumed that the trunk extending to the bi-level repeater BLR is the first one found to be idle and consequently the one selected. That being the case, switching relay 280, upon energizing in the usual manner at the end of the trunk hunting operation, extends conductors 227-229, inclusive, through to the corresponding conductors of the bi-level repeater BLR. As a further result of the energization of switch- 95 ing relay 280, it places a ground potential upon the discriminating wiper 282 at armature 279. This ground potential extends by way of discriminating conductor 283, resting contact of armature 284 and said 100 armature, upper trunk conductor 277, armature 407 and its resting contact, resting contact of armature 411 and said armature, and line relay 401 of the traffic separator TS to battery. Upon energizing, line relay 401 105 places ground upon release trunk conductor 416 of the secondary switch SS²⁴ by way of armature 406 of line relay 402 and its resting contact, thereby closing a circuit for switching relay 403. Relay 403, upon en- 110 ergizing, disconnects line relay 402 from trunk conductor 278 at armature 408; disconnects line relay 401 from trunk conductor 277 at armature 407, and at armatures 407 and 409 and their working contacts con- 115 nects trunk conductors 277 and 278 with trunk conductors 415 and 417 of the secondary switch SS²⁴. The line relay of the secondary switch SS²⁴, upon energizing over conductor 277, starts the trunk hunting op- 120 eration of the switch in the usual manner at its two upper armatures, and at its lower armature places ground upon release trunk conductor 416, thereby establishing a holding circuit for switching relay 403 before 125

the slow acting line relay 401 has had time to deenergize. The secondary switch SS²⁴ now proceeds to select an idle trunk in the usual manner, which trunk it will be assumed is the one extending to the repeater R¹³. That being the case, the line and release relays of the repeater R¹³, upon energizing, close a bridge across the associated outgoing trunk conductors and establish the usual holding circuit for the traffic separator TS and the secondary switch SS²⁴. In response to the bridge being closed across the associated inter-office trunk conductors by the line relay of the repeater R¹³, the line and release relays (not shown) of the selector G⁵ energize, thereby, preparing the switch for operation in the usual manner.

Returning now to the bi-level repeater BLR, line relay 270, upon energizing in response to the repeater being seized, prepares the usual bridge for conductors 277 and 278 at armature 274. This bridge, however, is open at another point as may be seen. As a further result of energization of line relay 270, it closes a circuit for release relay 271 at armature 273. Release relay 271, upon energizing, places ground upon the associated release trunk conductor at armature 276, thereby establishing the usual holding circuit for the selectors E' and F' and the secondary switch SS¹⁷. As a further result of energization of release relay 271, it closes a circuit for relay 272 at armature 275. This relay is designed and wound so as to allow time for the traffic separator TS to function as hereinbefore described before the said relay 272 operates. Upon energizing, relay 272 removes the discriminating ground from trunk conductor 277 and completes the usual bridge across conductors 277 and 278 at armature 284.

In Dunham the selector F, (Fig. 11,) to which the connection to Dunham has been extended, raises its wipers to the seventh level, in response to the seven interruptions produced in the circuit of its line relay by the line relay of the repeater R in response to the calling of the third letter in the desired number, and rotates them in search of an idle trunk in the usual manner. It will be noted that the seventh level of the selector F is dead. Consequently, the trunk selecting operation of the said selector F is of no avail at this time.

In the universal switcher US', Fig. 1, line relay 36, upon responding to the seven interruptions produced in its circuit upon the calling of the third letter of the desired number, in addition to opening the circuit of impulse relays 68 and 69 at armature 46, as hereinbefore explained, sends seven impulses of current to stepping magnet 80 by way of series relay 38. By the operation of stepping magnet 80, the wiper 82 is advanced step by step until it comes to rest

upon the seventh associated bank contact 88. Relay 38 is energized in series with stepping magnet 80, and, being slow acting, retains its armature attracted throughout the stepping movement, thereby maintaining the circuit of release magnet 81 open at armature 51 after off normal contacts 79 close upon wiper 82 being moved from its normal position. At the end of the stepping movement, series relay 38, upon deenergizing, closes the circuit of release magnet 81 at armature 51 by way of off normal contacts 79. A branch of this circuit extends by way of armature 83 and its resting contact, wiper 82, the seventh associated bank contact 88, working contact of armature 55 and said armature, and seizing relay 65 to battery. Upon energizing, seizing relay 65 closes a locking circuit for itself at the lightly adjusted armature 73, before its initial circuit is opened by release magnet 81. Release magnet 81, upon energizing, disconnects wiper 82 at armature 83 and restores it to normal position in the usual manner, the circuit of release magnet 81 being opened at off normal contacts 79 when wiper 82 reaches normal position. As a further result of the energization of seizing relay 65, it connects release trunk conductor 33 with release trunk conductor 92 of the secondary switch SS⁵ at armature 73; connects line conductors 32 and 34 with conductors 91 and 93 at armatures 71 and 75, and at armature 72 closes a circuit for cut off relay 35. Cut off relay 35, upon energizing, removes ground from armature 47 of line relay 36 at armature 45, thereby opening the circuit of release relay 37, and at armatures 43 and 44 disconnects conductors 32 and 34 from the windings of line relay 36. Line relay 36, upon deenergizing, opens the circuit of impulse relays 68 and 69 at armature 46. Impulse relay 68, upon deenergizing, removes the local bridge from across conductors 91 and 93 at armature 76, leaving line relay 126 of the repeater R' under the direct control of the calling substation. Impulse relay 69, upon deenergizing, removes the local bridge from across conductors 94 and 96 at armature 77, whereupon the connection to Dunham is released in the usual manner. Release relay 37, upon deenergizing, opens the locking circuit of relays 39 and 40 at armature 49, whereupon relays 39 and 40 deenergize, and at armature 48 removes ground from release trunk conductor 33, leaving the said conductor grounded by way of the holding circuit which extends back from armature 130 of release relay 127 of the repeater R', Fig. 4.

The calling subscriber now operates his calling device in accordance with the first digit 3 in the desired number, thereby producing three interruptions in the circuit of line relay 126 of the repeater R'. These

interruptions are relayed at armature 129 to line relay 270 of the bi-level repeater BLR, Fig. 6, and from thence to the incoming selector G⁵, Fig. 8, by way of the repeater R¹³, Fig. 7. The selector G⁵ now 5 raises its wipers to the third level and rotates them in search of an idle trunk. In the present case it will be assumed that the trunk extending to the selector H is the 10 first one found to be idle and consequently the one selected. That being the case, the selector H is prepared for operation in the usual manner.

In response to the calling of the second 15 digit 4 in the desired number, the selector H raises its wipers to the fourth level and receives them in search of an idle trunk. It will be assumed that the trunk extending to the connector J is the first one found 20 to be idle and consequently the one selected. That being the case, line relay 433, upon energizing in response to the seizure of the connector J, closes a circuit for release relay 434 at armature 450. Release relay 434, 25 upon energizing prepares a circuit for vertical magnet 471 and opens a point in the circuit of release magnet 470 at armature 453; places ground upon armature 458 of 30 busy relay 438 at armature 452; and at armature 451 places ground upon release trunk conductor 431, thereby establishing the usual holding circuit for the selectors G⁵ and H.

In response to the calling of the next digit 35 5 in the desired number, five interruptions are produced in the circuit of line relay 433 of the connector J. Each time line relay 433 deenergizes in response to one of these interruptions, it sends an impulse of current 40 to vertical magnet 471, the first impulse of current being sent over the following circuit: From ground by way of armature 450 and its resting contact, armature 453 and its working contact, resting contact of off 45 normal spring 469 and said spring, relay 435, and vertical magnet 471 to battery. By the operation of vertical magnet 471, the wipers 481-483, inclusive, are raised step by step until they stand opposite the fifth level 50 of bank contacts, which is the level in which the line of substation A' terminates. Relay 435 is energized in series with vertical magnet 471 and, being slow acting, retains its armature 454 attracted throughout the 55 vertical movement, thereby maintaining its own circuit and that of vertical magnet 471 intact after the off normal springs shift as they do upon the first vertical step. At the end of the vertical movement, slow acting 60 relay 435, upon deenergizing, shifts the impulse circuit from the vertical to the rotary magnet at armature 454.

The calling subscriber now operates his calling device in accordance with the next 65 and last digit 6 in the desired number,

whereupon six interruptions are produced in the circuit of line relay 433 of the connector J. Each time line relay 433 deenergizes in response to one of these interruptions, it sends an impulse of current to 70 rotary magnet 472 by way of the following circuit. From ground by way of armature 450 and its resting contact, armature 453 and its working contact, normally open contacts controlled by off normal spring 459, armature 454 and its resting contact, resting contact of armature 459 and said armature, armature 466 and its resting contact, and rotary magnet 472 to battery. By the operation of rotary magnet 472, the wipers 80 481-483, inclusive, are rotated step by step until they come to rest upon the sixth set of bank contacts in the fifth level, which set comprises bank contacts 484-486, inclusive. Relay 439 is energized in multiple with 85 rotary magnet 472 and, being slow acting, retains its armature attracted throughout the rotary movement. Upon energizing, relay 439 disconnects test wiper 482 from the upper winding of switching relay 440 and connects it to busy relay 438 at armature 461, and at armature 462 places a shunt around 90 armature 459 and its resting contact so as to render its own circuit and that of stepping magnet 472 independent of armature 459 which armature is attracted by busy relay 438 in case test wiper 482 is rotated over 95 grounded test contacts.

It will be assumed first that the line of 100 substation A' is busy when called. That being the case, test contact 485 is grounded and busy relay 438 is accordingly energized when test wiper 482 arrives upon the test contact of the called line. That being the case, relay 439, upon deenergizing at the 105 end of the rotary movement, disconnects itself and rotary magnet 472 from the impulse circuit at armature 462 (armature 459 having been operated) and at armature 461 opens the initial circuit of and completes a locking circuit for busy relay 438, the locking circuit being as follows: From ground by way of the working contact of armature 452 of release relay 434 and said armature, 110 armature 458 and its working contact, normally closed contacts controlled by armature 461, and relay 438 to battery. As a further result of the energization of busy relay 438, it connects a lead from the busy signalling machine B to the lower heavy 115 talking conductor. Consequently, the calling subscriber hears at this time the tone produced by said busy machine B and is informed thereby that he cannot obtain the desired connection for the time being. Upon 120 hearing this busy tone, the calling subscriber replaces his receiver, whereupon the entire connection is released in a manner to be hereinafter described.

It will be assumed now that the line of 130

substation A' is idle when called as hereinbefore described. That being the case, busy relay 438 is not energized at the end of the rotary movement and slow acting relay 439, 5 upon deenergizing, closed a circuit for switching relay 440 in series with switching relay 488 of the line switch C' of the called line as follows: From ground by way of the working contact of armature 452 of release relay 434 and said armature, armature 458 and its resting contact, upper winding of switching relay 440, resting contact of armature 461 and said armature, test wiper 482, test contact 485, private normal conductor 10 487, switching relay 488, and stepping magnet 490 to battery. Switching relays 440 and 448 energize in series over this circuit. Stepping magnet 490, however, does not energize at this time on account of the high resistance 15 of switching relay 488. Switching relay 488, upon energizing, clears the called line of its normal battery and ground connections, but owing to the usual mechanical inter-locking device (not shown) between its armature 20 and the armature of line relay 489, the armature of switching relay 488 is operated only about half way and consequently the switch wipers are not connected up.

In the connector J, switching relay 440, 30 upon energizing, closes a locking circuit for itself at its lightly adjusted armature 465, which armature is adjusted to make contact with its working contact before the other armatures of the relay are operated; disconnects rotary magnet 472 and relay 439 from the impulse circuit at armature 466 so as to render ineffective any further operation of the calling subscriber's calling device; places direct ground upon test wiper 482 at armature 464; and at armatures 463 and 467 connects up line wipers 481 and 483. Ringing current is now projected out over the called line intermittently by the ringing machine RM. This ringing current returns by way 40 of the bridged bell and condenser at the called substation, and the upper winding of ring cut off relay 437. Owing to the fact that ringing current is passing through the upper winding of ring cut off relay 437, an alternating E. M. F. is induced in the lower winding thereof, thereby sending a ringing tone back to the calling subscriber by way 45 of the lower winding of back bridge impedance 436, and the lower heavy talking conductor.

When the called subscriber responds to the ringing of his bell by removing his receiver, a direct current bridge is placed 50 across the conductors of the called line. Ring cut off relay 437, upon energizing over the called line, closes a locking circuit for itself and places ground on the lower winding of back bridge impedance 436 at its 55 lightly adjusted armature 456, which armature is adjusted to come into engagement

with its working contact before the other armatures have moved, and at armatures 455 and 457 disconnects its own upper winding and the generator lead and connects the called line with the upper and lower windings of back bridge impedance 436. 70

The calling and called subscribers may now converse with each other in the usual manner, the talking circuits being outlined by the heavy conductors, and after the conversation is terminated as any conversation does, regardless of its nature, the calling and called subscribers replace their receivers. 75

Release of connection from Lincoln office to 80 Market office.

When the receiver is replaced at substation A', the circuit of back bridge impedance 436 is opened, and when the receiver is replaced at the calling substation, the circuit 85 of line relay 126 of the repeater R' is opened. Line relay 126, upon deenergizing, opens the circuit of release relay 127 at armature 128 and at armature 129 opens the circuit of line relay 270 of the bi-level repeater BLR. 90 Line relay 270, upon deenergizing, opens the circuit of release relay 271 at armature 273 and at armature 274 opens the circuit of the line relay of the repeater R¹³. The line 95 relay of the repeater R¹³, upon deenergizing, in addition to opening the circuit of the associated release relay, opens the circuit of line relay 433 of the connector J. Line relay 433 of the connector J, upon deenergizing, opens the circuit of release relay 434 at 100 armature 450.

Returning now to the repeater R', Fig. 4, release relay 127, upon deenergizing in response to the prolonged opening of its circuit, removes ground from release trunk conductor 119 at armature 130, thereby rendering the repeater R', the universal switcher US', the selector D, and the line switch C idle. As a further result of the ground potential being removed from release trunk conductor 119, switching relay 101 of the switch SS⁵, seizing relay 65 and cut off relay 35 of the universal switcher US', the switching relay (not shown) of the selector D, and switching relay 5 of the line switch C deenergize. 110 This restores conditions to normal in the switches named, with the exception of the selector D, of which the wipers are restored to normal position in the usual manner upon the energization of the associated release magnet (not shown). 115

In the bi-level repeater BLR, release relay 271, upon deenergizing in response to the prolonged opening of its circuit by line 125 relay 270, opens the circuit of relay 272 at armature 275, whereupon the said relay 272 deenergizes, and at armature 276 removes ground from the associated release trunk conductor, thereby rendering the repeater BLR, secondary switch SS¹⁷, and the selec- 130

tor F' idle. As a further result of the ground potential being removed from the release trunk conductor of repeater BLR, switching relay 280 of the secondary switch 5 SS¹⁷, the switching relay (not shown) of the selector F', and switching relay 169 of the selector E' deenergize. The deenergization of switching relay 280 of the secondary switch SS¹⁷ restores conditions in that switch 10 to normal, and the deenergization of the switching relays of the selectors E' and F' closes the circuits of the associated release magnets, whereupon the switches are restored to normal position in the usual manner, the circuit of release magnet 170 of the selector E' being as follows: From ground 15 by way of the resting contact of armature 184 of switching relay 169 and said armature, armature 176 and its resting contact, armature 178 and its resting contact, off normal contacts 171, and release magnet 170 to battery. The circuit of release magnet 170 is opened at off normal contacts 171 by the switch shaft when the latter reaches 20 normal position.

In the repeater R¹⁸, the release relay thereof, upon deenergizing in response to the prolonged opening of its circuit by the associated line relay, removes ground from the 25 associated release trunk conductor, thereby rendering the repeater R¹⁸ idle. As a further result of the ground potential being removed from the release trunk conductor of the repeater R¹⁸, the switching relay of the 30 secondary switch SS²⁴ and switching relay 403 of the traffic separator TS deenergize, thereby restoring conditions in the traffic separator TS and the secondary switch SS²⁴ to normal.

40 In the connector J, release relay 434, upon deenergizing, removes ground from armature 458 of busy relay 438 at armature 452, and at armature 451 removes ground from release trunk conductor 431, whereupon ring 45 cut off relay 437, switching relay 440 and the switching relays (not shown) of the selectors G⁵ and H deenergize. When this occurs the selectors named are restored to normal position in the usual manner. The de- 50 energization of switching relay 440 disconnects the line wipers at its upper and lower armatures, and removes the busy potential from the test contact of the called line at armature 464. As a further result of the de- 55 energization of release relay 434, it closes at armature 433 a circuit for release magnet 470 by way of off normal contacts 468. In response to the energization of release mag- 60 net 470, the shaft and wipers of the connector J are restored to normal position in the usual manner, the circuit of release magnet 470 being opened at off normal contacts 65 468 by the switch shaft when the latter reaches normal position. The entire connection is now released, the busy potential is removed

from the test contacts of the calling and called line, and the common equipment used to extend the connection is restored to common use.

Call from Lincoln to Maburn.

70

It will be assumed now that the subscriber at substation A calls a subscriber whose line terminates in Maburn, Fig. 10, the first two letters of which are the same as the first 75 two letters of Market. When the receiver is removed at substation A, the line switch C operates in the hereinbefore described manner to select an idle first selector, which selector it will be assumed is the selector D. 80

In response to the calling of the first letter M in the desired number, the selector D raises its wipers to the fifth level and rotates them in search of an idle trunk. In the present case it will be assumed that the trunk extending to the universal switcher US' is the first one found to be idle and consequently the one seized. That being the case, line and release relays 36 and 37 energize and the latter establishes the usual holding circuit for the selector D and the line switch C. As a result of the energization of line relay 36, it closes a circuit for impulse relays 68 and 69, whereupon the associated secondary switches SS⁵ and SS² operate in the usual 90 manner to select idle trunks, which trunks it will be assumed are the ones extending to the repeaters R and R'. That being the case, the selector E', Fig. 5, in Medbury, Fig. 11, and the selector E in Dunham, Fig. 11, are prepared for operation in the usual manner.

95

100

In response to the calling of the second letter A in the desired number, one interruption is produced in the circuit of line relay 105 36 of the universal switcher US', Fig. 1. This interruption is repeated to impulse relays 68 and 69 at armature 46, which impulse relays in turn repeat it to the line relays of the repeaters R and R', from whence it is repeated to the distant associated selectors E and E'.

110

In response to the one interruption produced in the circuit of its line relay 165, the selector E', Fig. 5, raises its wipers to 115 the first level and selects an idle second selector in the usual manner, which selector it will be assumed is the selector F'.

120

In response to the one interruption produced in the circuit of its line relay, the selector E, in Dunham, Fig. 11, raises its wipers to the first level and selects an idle trunk in the usual manner, which trunk it will be assumed is the one extending to the selector F.

125

The calling subscriber now operates his calling device in accordance with the third letter B in the desired number, whereupon two interruptions are produced in the line relay of the selector F'. Figs. 5 and 11, and 130

likewise in the circuit of the line relay of the selector F, Fig. 11.

In response to these two interruptions produced in the circuit of its line relay, the selector F' raises its wipers to the second level and rotates them in search of an idle trunk. The second level of the selector F', however, is dead, and consequently its trunk selecting operation is of no avail at this time.

10 In response to the two interruptions produced in the circuit of its line relay, the selector F, Fig. 11, raises its wipers to the second level and selects an idle trunk, which trunk it will be assumed is the one extending to the secondary switch SS¹⁴. That being the case, the secondary switch SS¹⁴ selects an idle repeater, the repeater R⁶ for example. When this occurs, the incoming selector (not shown) in Maburn, is prepared for operation 20 in the usual manner.

In the universal switcher US', Fig. 1, in response to the calling of the second letter A in the desired number, relays 39 and 40 become energized and locked up in the hereinbefore described manner, and in response to the calling of the third letter B in the desired number, line relay 36 sends two impulses to stepping magnet 80, whereupon the wiper 82 is advanced into engagement with the second bank contact 85. When series relay 38 deenergizes at the end of the stepping movement, it closes the usual circuit for release magnet 81 by way of off normal contacts 79, whereupon the wiper 82 is restored to normal and off normal contacts 79 are opened in the usual manner. Before release magnet 81 energizes after its circuit is closed, a branch of its circuit extends by way of armature 83 and its resting contact, 30 wiper 82, bank contact 85, working contact of armature 56 and said armature, and relay 66 to battery. Relay 66, upon energizing, closes a locking circuit for itself at armature 62 before release magnet 81 has had 40 time to energize; connects release trunk conductor 33 with release trunk conductor 95 of the secondary switch SS² at armature 63; connects line conductors 32 and 34 with conductors 94 and 96 of the secondary switch 50 SS² at its upper and lower armatures; and at armature 61 closes a circuit for cut off relay 35. Cut off relay 35, upon energizing, removes ground from armature 47 of line relay 36 at armature 45, and at armatures 43 and 55 44 disconnects conductors 32 and 34 from the windings of line relay 36. Line relay 36, upon deenergizing, opens the circuit of impulse relays 68 and 69 at armature 46. Relay 68, upon deenergizing, opens the local bridge across conductors 91 and 93, whereupon the connection to Medbury is released in the usual manner. Impulse relay 69, upon deenergizing, removes the local bridge from across conductors 94 and 96 at armature 77, leaving the line relay of the repeater

R under the direct control of the substation A. Release relay 37, upon deenergizing, opens the locking circuit of relays 39 and 40 at armature 49, whereupon they both deenergize, and at armature 48, removes ground from release trunk conductor 33, leaving the said conductor grounded by way of the holding circuit which extends back from the armature of the release relay of the repeater R.

The calling subscriber now dials the four digits in the desired number, whereupon the connection is extended to the desired line in the usual manner.

Call local to Lincoln.

80

It will be assumed now that the subscriber at substation A desires to converse with a subscriber whose line terminates in Lincoln which is the office in which the line at substation A terminates. Upon referring to the calling device shown in Fig. 9, it will be seen that the numerical equivalent of the first two letters L and I is 51 and is the same as the numerical equivalent of the first two letters of Market and Maburn. Consequently, when a subscriber is calling a subscriber whose line terminates in Lincoln it cannot be determined until the third letter is dialled whether the call is intended for Lincoln, for 90 Maburn or Market. It will be assumed further that the subscriber at substation A has removed his receiver and that he has dialled the first two letters L and I. It will be assumed still further that the connection 100 has taken the previously pointed out path to the selectors F and F', in Dunham and Medbury, respectively, by way of the universal switcher US', and consequently that relays 39 and 40 of the universal switcher US' are 105 energized and locked up as a result of the calling of the second letter I in the desired number.

In response to the calling of the third letter N in the desired number, six interruptions are produced in the circuit of line relay 36 of the universal switcher US' and are relayed in the usual manner to the selector F, Fig. 11, and the selector F', Figs. 11 and 5. The sixth level of the selector F is dead and consequently its trunk selecting operation is of no utility at this time. The selector F', upon operating, selects an idle trunk in the sixth level with the result that a secondary switch, the secondary switch SS¹⁸, for example, is seized. The secondary switch SS¹⁸, upon operating, selects an idle trunk to Pontiac by way of bi-level repeater BLR. It will be suffice to say that the connection established by way of the secondary switch SS¹⁸ is merely an incidental operation and that it is released immediately after having been established as will be hereinafter explained.

In the universal switcher US' line relay 130

36, upon deenergizing in response to each of the six interruptions produced in its circuit in response to the calling of the third letter N in the desired number, not only interrupts the circuit of impulse relays 68 and 69 as explained, but also, sends six impulses of current to stepping magnet 80 by way of series relay 38. As a result of the operation of stepping magnet 80, wiper 82 is advanced step by step into engagement with the sixth associated bank contact 87. When the circuit of release magnet 81 is closed at the end of the stepping movement by series relay 38, wiper 82 is restored to normal position in the usual manner. However, while wiper 82 is still upon bank contact 82, after the circuit of release magnet 81 is closed and before the said magnet 81 has had time to energize, a branch of the circuit of release magnet 81 extends by way of armature 83 and its resting contact, wiper 82, bank contact 87, working contact of armature 57 and said armature and seizing relay 67 to battery. Seizing relay 67, upon energizing, closes the usual locking circuit for itself before release magnet 81 has had time to energize; connects the line and release trunk conductors through to the corresponding conductors of the secondary switch SS^{26} ; and closes the circuit of cut off relay 35. In response to the energization of cut off relay 35, the circuits of release relay 37 and line relay 36 are opened in the usual manner. When line relay 36 deenergizes it opens the circuit of impulse relays 68 and 69 at armature 46, whereupon the connections to Dunham and to Medbury are released in the usual manner in response to the deenergization of relays 68 and 69.

40 The secondary switch SS^{26} , upon operating in response to being seized, selects an idle local selector, the selector G' for example. Line relay 97 of the selector G', upon energizing, closes a circuit for release relay 98. Release relay 98, upon energizing, opens a point in the circuit of the release magnet and prepares a circuit for the vertical magnet at armature 100, and at armature 99 places ground upon the associated release trunk conductor thereby establishing the usual holding circuit for the secondary switch SS^{26} , the universal switcher US', the selector D, and the line switch C.

55 In response to the calling of the first digit in the desired number the selector G' raises its wipers to the desired level and selects an idle hundreds selector in the usual manner, and in response to the calling of the three remaining digits in the desired number the hundreds selector seized by the selector G', and a connector are operated to extend the connection to the desired line in the usual manner.

Call from Lincoln to Medbury.

65 It will be assumed now that the subscriber

at substation A desires to converse with a subscriber whose line terminates in Medbury. It will be assumed further that when the receiver is removed at the calling substation the selector D is the one seized, and that when the first letter M in the desired number is dialled the universal switcher US' is the one seized by the selector D. It will be assumed still further that the secondary switches SS^2 and SS^6 , upon operating in response to the seizure of the universal switcher US', seize the repeaters R and R', respectively, and consequently that the distant associated selectors E and E' are prepared for operation in the usual manner.

70 The calling subscriber now dials the second letter E in the desired number, whereupon three interruptions are produced in the circuit of the line relay of the selectors E and E' in the hereinbefore described manner. The selector E, Fig. 11, upon responding to these three interruptions, selects an idle trunk, which trunk it will be assumed is the one extending to the selector F. The selector E', Figs. 11 and 5, upon responding to these three interruptions, selects an idle trunk, which trunk it will be assumed is the one extending to the selector F'.

75 The universal switcher US', line relay 36, upon deenergizing in response to each of the three interruptions produced in its circuit at this time, in addition to repeating these interruptions to impulse relays 68 and 69, sends three impulses of current to the associated stepping magnet 80, whereupon the wiper 82 is advanced step by step into engagement with the third bank contact 86. When series relay 38 deenergizes at 80 the end of the stepping movement, it closes the usual circuit for release magnet 81. A branch of this circuit extends by way of armature 83 and its resting contact, wiper 82, bank contact 86, resting contact of armature 53 and said armature, relay 41, and cut off relay 39 to battery. Relay 41, upon energizing, closes a locking circuit for itself and relay 39 at armature 58, prepares a circuit for relay 65 at armature 59, and at armature 60 prepares a circuit for relay 66. Cut off relay 39, upon energizing, disconnects relay 40 at armature 52, and at armature 53 opens its own initial circuit and that of relay 41. Release magnet 81, upon energizing, restores wiper 82 to normal in the usual manner.

85 100 105 110 115 120 125 Relay 40, it may be stated, is adjusted so as to operate armature 58 quickly but not to operate its other armatures until after a sufficient time has elapsed to allow release magnet 81 to disconnect wiper 82. This insures that relay 65 does not have a chance to operate prematurely when its circuit is prepared at armature 59.

In response to the calling of the third let-

ter D in the desired number, the selector F, Fig. 11, and selector F', Figs. 11 and 5, raise their wipers to the third level and rotate them in search of idle trunks. The third 5 level of the selector F, however, is dead, and consequently its trunk selecting movement is of no avail at this time. The selector F', upon raising its wipers to the third level, selects an idle trunk, which trunk it will be 10 assumed is the one extending to the selector G².

In the universal switcher US', line relay 36, upon responding to the calling of the third letter D in the desired number, sends 15 three impulses of current to stepping magnet 80, whereupon wiper 82 is again advanced into engagement with the third associated bank contact 86. Upon deenergizing at the end of the stepping movement, series 20 relay 38 closes the usual circuit for release magnet 81 at armature 51, whereupon wiper 82 is restored to normal in the usual manner. A branch of the circuit of release magnet 81, however, extends by way of armature 83 and its resting contact, wiper 82, bank 25 contact 86, working contact of armature 59 and said armature, and relay 65 to battery. Relay 65, upon energizing, closes a locking circuit for itself at armature 73 before 30 release magnet 81 has had time to energize. As a further result of the energization of seizing relay 65, the connection is extended through to the conductors of the secondary switch SS⁵, and the connection to 35 Dunham is released in the hereinbefore described manner.

In response to the calling of the four digits in the desired number, the selector G², a local hundreds selector, and a connector are 40 operated to extend the connection to the desired line in the usual manner.

Call from Lincoln to Meadow.

It will be assumed now that the subscriber 45 at substation A calls a subscriber whose line terminates in Meadow. It will be assumed further that the removing of the receiver and the calling of the first two letters M and E in the desired number results in the 50 connection being extended over the identical paths taken in the previous example, when the letters M and E of Medbury were called. That being the case, the connection is extended to the selector F' in Medbury, Figs. 55 5 and 11, and to the selector F in Dunham, Fig. 11, after the second letter E has been called.

In response to the calling of the third letter A in the desired number, a single inter- 60 ruption is produced in the circuit of the line relays of the selector F and F'. The selector F', upon raising its wipers to the first level, rotates them in search of an idle trunk. The first level of bank contacts, 65 however, is dead, and consequently the trunk

selecting operation is of no avail at this time.

The selector F, upon raising its wipers to the first level, selects an idle trunk which trunk it will be assumed is the one extending to the secondary switch SS¹⁵. The secondary switch SS¹⁵, upon being seized, selects an idle repeater, the repeater R' for example, whereupon the distant associated selector in Meadow is prepared for operation in the usual manner.

In the universal switcher US', Fig. 1, a single impulse of current is delivered to stepping magnet 80 when the third letter A in the desired number is called, whereupon wiper 82 is advanced into engagement with the first associated bank contact 84. When the circuit of release magnet 80 is closed, upon the deenergization of series relay 38, a branch thereof extends by way of armature 83 and its resting contact, wiper 82, bank 85 contact 84, working contact of armature 60 and said armature, and seizing relay 66 to battery. In response to the energization of seizing relay 66, the route to Dunham is definitely seized, cut off relay 35 is energized 90 with the hereinbefore described results, and the connection to Medbury is released in the usual manner.

In response to the calling of the four digits in the desired number, the connection is extended to the desired line in the usual manner.

Call from Lincoln to Cedar.

It will be assumed now that the subscriber 100 at substation A desires to converse with a subscriber whose line terminates in Cedar, Figs. 10 and 11, which office is reached by way of Blazon as a switching center. It will be assumed further that, when the receiver is removed at substation A, the individual line switch C selects the trunk extending to the selector D.

The calling subscriber now operates his calling device in accordance with the first 110 letter C in the desired number, whereupon the selector D raises its wipers to the second level and selects an idle trunk, which trunk it will be assumed is the one extending to the universal switcher US⁴, Fig. 2. Upon 115 energizing in response to the seizure of the associated trunk, line relay 302 of the universal switcher US⁴ closes a circuit for release relay 303 at armature 324. Release relay 303, upon energizing, prepares a circuit 120 for stepping magnet 310 at armature 327; prepares a locking circuit for relay 305 at armature 326; and at armature 325 places ground upon release trunk conductor 29, thereby establishing the usual holding circuit 125 for the selector D and the line switch C. As a further result of the energization of line relay 302, it closes a circuit for impulse relay 309 at armature 323. Relay 309, upon energizing, places a local bridge across 130

the line conductors of the associated secondary switch SS^s at armature 337. It will be assumed that the secondary switch SS^s , upon operating, seizes the trunk extending to the repeater R^2 . That being the case, the selector E^2 , Fig. 11, in Blazon, is prepared for operation in the usual manner.

In response to the calling of the second letter E of the desired number, the circuit of line relay 302 of the universal switcher US^4 is interrupted three times momentarily. These interruptions are repeated at armature 323 in the circuit of impulse relay 309, which relay interrupts the circuit of the line relay of the repeater R^2 three times at armature 337. The line relay of the repeater R^2 , upon deenergizing in response to each of the three momentary interruptions produced in its circuit, opens the circuit of the line relay of the selector E^2 , Fig. 11, in Blazon. As a result, the selector E^2 raises its wipers to the third level and selects an idle trunk, which trunk it will be assumed is the one extending to the selector F^2 .

In the universal switcher US^4 , as a further result of each of the three momentary deenergizations of line relay 302, it closes the following circuit for stepping magnet 310: from ground by way of the resting contact of armature 322 and said armature, armature 324 and its resting contact, armature 327 and its working contact, relay 304, and stepping magnet 310 to battery. By the operation of stepping magnet 310, wiper 332 is advanced step by step until it comes into engagement with the third associated bank contact 333. Relay 304 is energized in series with magnet 310 and, being slow acting, retains its armature attracted throughout the stepping movement, thereby maintaining the circuit of release magnet 311 open after off normal contacts 312 have closed as they do upon the wiper 332 being moved from its normal position. At the end of the stepping movement, series relay 304, upon deenergizing, closes at armature 328 a circuit for release magnet 311 by way of off normal contacts 312. Release magnet 311, upon energizing, restores wipers 332 to normal, its circuit being opened at off normal contacts 312 when wiper 332 reaches normal position. However, before release magnet 311 has had time to energize, which magnet has a comparatively heavy armature which is retained by a strong spring, relay 305 energizes in multiple with the said release magnet 311 by way of armature 313 and its resting contact, wiper 332, bank contact 333, normally closed contacts controlled by armature 329, and relay 305 to battery. Relay 305, upon energizing, closes a local locking circuit for itself and opens its initial circuit at armature 329; prepares a circuit for relay 305 at armature 330; and at armature 331 disconnects relay 308 from the fifth bank

contact 334 and connects it with the third bank contact 333. Relay 305, it may be said, is adjusted to close its local locking circuit at its lightly adjusted armature 329 immediately but not to operate its other and more stiffly adjusted armatures until after release magnet 311 has operated armature 313. Also, the normally closed contacts controlled by armature 329 are adjusted to open before armature 331 makes contact with its working contact. These adjustments insure that relay 308 is not prematurely operated as might otherwise be the tendency on account of the fact that it is connected to bank contact 333 upon the operation of armature 331.

The calling subscriber now operates his calling device in accordance with the third letter D in the desired number, whereupon the selector F^2 , Fig. 11, in Blazon, raises its wipers to the third level and selects an idle trunk, which trunk it will be assumed is the one extending to the secondary switch SS^{22} . It will be assumed that the switch SS^{22} , upon being seized, seizes the repeater R^{11} . When this occurs, the incoming selector (not shown) associated therewith in Cedar is prepared for operation in the usual manner.

In the universal switcher US^4 , line relay 302, upon deenergizing in response to each of the three momentary interruptions produced in its circuit, in addition to repeating these interruptions at armature 323, closes the usual circuit for stepping magnet 310 at armature 324, whereupon wiper 332 is again advanced into engagement with the third associated bank contact 333. Series relay 304, upon deenergizing at the end of the stepping movement, closes the usual circuit for release magnet 311. A branch of this circuit extends by way of armature 313 and its resting contact, wiper 332, bank contact 333, working contact of armature 331 and said armature, and seizing relay 308 to battery. Relay 308, upon energizing, closes a locking circuit for itself at armature 340; connects release trunk conductors 29 with the release trunk conductor of the secondary switch SS^s at armature 341; connects line conductors 28 and 30 with the corresponding conductors of the secondary switch SS^s at armatures 338 and 342; and at armature 339 closes a circuit for cut off relay 301. Cut off relay 301, upon energizing, removes ground from armature 324 of line relay 302 at armature 322, thereby opening the circuit of release relay 303, and at armatures 320 and 321 disconnects conductors 28 and 30 from the windings of line relay 302. Line relay 302, upon deenergizing, opens the circuit of impulse relay 309 at armature 323. Impulse relay 309, upon deenergizing, removes the local bridge from across the line conductors of the secondary switch SS^s , thereby leaving the line relay of the repeater R^2 under

the direct control of the calling substation. Release relay 302, upon deenergizing, opens the circuit of relay 305 at armature 326, whereupon the said relay 305 deenergizes; 5 and at armature 325 removes ground from release trunk conductor 29, leaving the said conductor grounded by way of the holding circuit which extends back from the armature of the release relay of the repeater R².
 10 The calling subscriber now operates his calling device in accordance with the four digits in the desired number, whereupon the thousands selector in Cedar to which the connection has been extended, a hundreds selector, and a connector are operated in the usual manner to extend the connection to the desired line. After the connection has been extended to the desired line and the conversation has been completed, the connection is released in the usual manner upon the receiver being replaced at the calling substation.

Call from Lincoln to Blazon.

25 It will be assumed that the subscriber at substation A desires to converse with a subscriber whose line terminates in Blazon. It will be assumed that after the calling subscriber has removed his receiver and dialled 30 the first letter B in the desired number, which letter appears in the same hole of the calling device shown in Fig. 11, as the first letter C in Cedar, the connection is extended to the selector E² in Blazon by way of 35 the previously pointed path, which includes the selector D, universal switcher US⁴, secondary switch SS⁸, and the repeater R².

That being the case, the selector E raises its wipers to the fifth level upon the calling 40 of the second letter L in the desired number and selects an idle trunk, which trunk it will be assumed is the one extending to the selector F⁸.

In the universal switcher US⁴, line relay 45 302, upon deenergizing in response to each of the five momentary interruptions produced in its circuit, closes the usual circuit for stepping magnet 310 with the result that wiper 332 is advanced into engagement 50 with the fifth associated bank contact 334. When the circuit of release magnet 311 is closed, upon the deenergization of series 55 relay 304, a branch thereof extends by way of armature 313 and its resting contact, wiper 332, bank contact 334, resting contact of armature 331 and said armature, and seizing relay 308 to battery. Relay 308, upon energizing, extends the conductors 60 28-30, inclusive, through to the corresponding conductors of the secondary switch SS⁸, and closes the circuit for cut off relay 301, which relay, upon energizing produces the hereinbefore described results.

When the calling subscriber operates his 65 calling device in accordance with the third

letter A in the desired number the selector F⁸ raises its wipers to the first level and selects an idle trunk, which trunk it will be assumed is the one extending to the local thousands selector G⁴.
 70

In response to the calling of the four digits in the desired number, the connection is extended from the selector G⁴, by way of a local hundreds selector, and a connector, to the desired line in the usual manner.
 75

Call from Lincoln to Beverly.

It will be assumed now that the subscriber at substation A desired to converse with a subscriber whose line terminates in Beverly. 80 The first two letters B and E of which appear in the same holes of the calling device shown in Fig. 9, as the first two letters C and E, respectively, of Cedar, the first letter B also being the same as the first letter B of Blazon. It will be assumed further that the calling subscriber has removed his receiver and dialled the first two letters B and E in the desired number, and that the connection has been extended to the selector 90 F² in Blazon over the path described in connection with the call to Cedar, which path extends by way of the universal switcher US⁴, Fig. 2.

The calling subscriber now operates his 95 calling device in accordance with the third letter V in the desired number, whereupon the selector F² in Blazon, Fig. 11, to which the connection has been extended, raises its wipers to the eighth level and rotates them 100 in search of an idle trunk. The eighth level of the selector F², however, is dead, and consequently its trunk selecting operation is of no avail at this time.

In the universal switcher US⁴, wiper 332 is 105 advanced into engagement with the eighth bank contact 335 at this time, and, upon the usual circuit being closed for release magnet 311, a branch thereof extends by way of armature 313 and its resting contact, wiper 110 332, bank contact 335, armature 330 and its working contact, and seizing relay 306 to battery. Relay 306, upon energizing, closes a locking circuit for itself at armature 345; connects release trunk conductor 29 with the 115 release trunk conductor of the secondary switch SS¹⁰ at armature 346; and at armatures 343 and 347 connects line conductors 28 and 30 with the line conductors of the secondary switch SS¹⁰. As a result of this, 120 the secondary switch SS¹⁰ operates in the usual manner to select an idle trunk, which trunk it will be assumed is the one extending to the repeater R⁴. That being the case, the associated incoming selector (not shown) 125 in Beverly is prepared for operation in the usual manner. As a further result of the energization of seizing relay 306, it closes at armature 344 a circuit for cut off relay 301, and cut off relay 301, upon energizing, 130

produces the hereinbefore described results, of which one is to disconnect line relay 302. Upon the deenergization of line relay 312, the circuit of impulse relay 309 is opened at 5 armature 323. Impulse relay 309, upon deenergizing, removes the local bridge from across the line conductors of the secondary switch SS⁸ at armature 337, whereupon the connection to Blazon is released in the usual 10 manner.

In response to the dialling of the digits in the desired number, the thousands selector in Beverly to which the connection has been extended, a hundreds selector, and a connector 15 are operated in the usual manner to extend the connection to the called line.

Call from Lincoln to Seminole.

It will be assumed now that the subscriber at substation A desires to converse with a subscriber whose line terminates in Seminole, which office is reached by way of Blazon as a switching center. It will be noted that the first letter S of Seminole is the same as the first letter S of Saxony and of South. When the receiver is removed at substation A, the line switch C operates to select an idle first selector, the first selector D for example, and when the calling device is turned in accordance with the first letter S in the desired number, the selector D raises its wipers to the seventh level and rotates them in search of an idle trunk, the trunk extending to the universal switcher US³, 25 Fig. 3, for example. In the universal switcher US³, line relay 351, upon energizing in response to the seizure of the associated trunk, closes a circuit for release relay 352 at armature 379. Release relay 352, 30 upon energizing, prepares a circuit for stepping magnet 361 at armature 382; prepares a locking circuit for relay 354 at armature 381; and at armature 380 places ground upon release trunk conductor 26, thereby establishing the usual holding circuit for the selector D and the line switch C. As a further result of the energization of line relay 351, it closes a circuit for impulse relay 358 at armature 378 by way of armature 384 and 35 its resting contact. Impulse relay 358, upon energizing, closes a local bridge across the line conductors of the secondary switch SS⁷. The switch SS⁷, upon operating, selects an idle trunk, which trunk it will be assumed 40 is the one extending to the repeater R². That being the case, the associated selector E² in Blazon is prepared for operation in the usual manner.

The calling subscriber now operates the dial of his calling device in accordance with the second letter E in the desired number, whereupon three interruptions are produced in the circuit of line relay 351 of the universal switcher US³. Upon deenergizing in response to each of these interruptions, line

relay 351 opens the circuit of impulse relay 358 at armature 378. Impulse relay 358 repeats these interruptions to the line relay of the repeater R² at armature 399, and the line relay of the repeater R² repeats these interruptions to the line relay of the selector E² in Blazon, Fig. 11. The selector E² raises its wipers to the third level and selects an idle trunk, the trunk extending to the selector F² for example. 75

In the universal switcher US³, line relay 351, upon deenergizing in response to each of the three interruptions produced in its circuit, in addition to interrupting the circuit of impulse relay 358 as described, sends an impulse of current to stepping magnet 361 over the following circuit: from ground by way of the resting contact of armature 377 and said armature, armature 379 and its resting contact, armature 382 and its working contact, relay 353, and stepping magnet 361 to battery. By the operation of stepping magnet 361, wiper 393 is advanced into engagement with the third associated bank contact 395. When series relay 353 falls 80 back at the end of the stepping movement, it closes a circuit for release magnet 362 at armature 383 by way of off normal contacts 363. Release magnet 362, upon energizing, disconnects wiper 393 at armature 364 and restores it to normal position, the circuit of release magnet 362 being opened at off normal contacts 363 when wiper 393 reaches normal position. However, release magnet 362, being adjusted similar to the release magnets of the universal switchers US and US⁴, is slightly slow in energizing and sufficient time is allowed for relay 357 to operate its lightly adjusted armature 390 before release magnet 362 energizes, relay 354 being energized in multiple with release magnet 362 by way of armature 364 and its resting contact, wiper 393, bank contact 395, and armature 386 and its resting contact. 85 Upon energizing, seizing relay 357, in addition to closing a locking circuit for itself at armature 390, connects release trunk conductor 26 with the release trunk conductor of the secondary switch SS⁷ at armature 391; connects line conductors 25 and 27 with corresponding conductors of the secondary switch SS⁷ at armatures 388 and 392; and at armature 389 closes a circuit for cut off relay 350. Cut off relay 350, upon energizing, removes ground from armature 379 of line relay 351 at armature 377, thereby opening the circuit of release relay 352, and at armatures 375 and 376 disconnects conductors 25 and 27 from the windings of line relay 351. Line relay 351, upon deenergizing, opens the circuit of impulse relay 358 at armature 378. Impulse relay 358, upon deenergizing, removes the local bridge from across the line conductors of the secondary switch SS⁷, leaving the line relay of the re- 90 95 100 105 110 115 120 125 130

peater R^2 under the direct control of the calling substation. Release relay 352, upon deenergizing, removes ground from release trunk conductor 26, leaving the said conductor grounded by way of the holding circuit which extends back from the armature of the release relay of the repeater R^2 .

The calling subscriber now operates his calling device in accordance with the third letter M in the desired number, whereupon the selector F^2 , Fig. 11, in Blazon, raises its wipers to the fourth level and selects an idle trunk to Seminole by way of a secondary switch and a repeater, the secondary switch SS^{23} and the repeater R^{12} for example.

In response to the calling of the four digits in the desired number, the thousands selector in Seminole to which the connection has been extended, a hundreds selector, and a connector are operated in the usual manner to extend the connection to the desired line. After the connection has been completed and the conversation has terminated, the connection is released in the usual manner upon the receiver being replaced at the calling substation.

Call from Lincoln to Saxony.

It will be assumed now that the subscriber at substation A desires to converse with a subscriber whose line terminates in Saxony. It will be assumed further that, after the calling subscriber has removed his receiver and dialled the first letter S in the desired number, the connection is extended by way of the selector D, Fig. 1, the universal switcher US^3 , Fig. 3, secondary switch SS^1 , and the repeater R^2 to the selector E^2 in Blazon, Fig. 11, which is the path over which the connection was extended in the previous example upon the calling of the first letter S in the desired number.

When the calling subscriber operates his calling device in accordance with the second letter A in the desired number, the selector E^2 in Blazon, raises its wipers to the first level and selects an idle trunk, the trunk extending to the selector F^3 for example. In the universal switcher US^3 the wiper 93 is brought into engagement with the first bank contact 394 and upon the circuit of release magnet 362 being closed at the end of the stepping movement, relay 357 is energized over the previously traced circuit and, upon energizing, definitely seizes the trunk to Blazon in the hereinbefore described manner.

In response to the calling of the third letter X in the desired number, the selector F^3 , Fig. 11, raises its wipers to the ninth level and seizes an idle secondary switch, the secondary switch SS^{20} for example, whereupon an idle repeater is seized, the repeater R^9 for example. That being the case,

the thousands selector in Saxony (not shown) which is associated with the repeater R^9 is prepared for operation in the usual manner.

In response to the calling of the four digits in the desired number, the local switches in Saxony are operated in the usual manner to extend the connection to the desired line.

Call from Lincoln to South.

It will be assumed now that the subscriber at substation A desires to converse with a subscriber whose line terminates in South, and that he has removed his receiver and dialled the first letter S in the desired number with the result that the connection is extended to the selector E^2 in Blazon over the hereinbefore pointed out path which includes the universal switcher US^3 .

In response to the calling of the second letter O in the desired number, the selector E^2 in Blazon raises its wipers to the tenth level and rotates them in search of an idle trunk. The tenth level of the selector E^2 , however, is dead, and consequently the trunk selecting operation of the said selector E^2 is of no avail at this time.

In the universal switcher US^3 , the wiper 393 is brought into engagement with the tenth associated bank contact 398 and, upon the circuit of release magnet 362 being closed, a branch thereof extends by way of armature 364 and its resting contact, wiper 393, bank contact 398, normally closed contacts controlled by armature 385, and relay 354 to battery. Relay 354, upon energizing, closes a locking circuit for itself and opens its initial circuit at armature 385; opens a point in the circuit of seizing relay 357 at armature 386; prepares a circuit for seizing relay 359 at armature 387; and at armature 384 opens the circuit of impulse relay 358, whereupon the connection to Blazon is released in the usual manner.

In response to the calling of the next letter U in the desired number, the circuit of line relay 351 of the universal switcher US^3 is opened eight times momentarily and as a result of the eight deenergizations thereby caused, wiper 393 is advanced into engagement with the eighth associated bank contact 397 by the operation of stepping magnet 361. When the circuit of release magnet 362 is closed at the end of the vertical movement, a branch thereof extends by way of armature 364 and its resting contact, wiper 393, bank contact 397, armature 387 and its working contact, and seizing relay 359 to battery. Relay 359, upon energizing, closes the usual locking circuit for itself; extends the line and release trunk conductors through to the corresponding conductors of the switch SS^9 ; and closes a circuit for cut off relay 350. In response to the energization of cut off

relay 350, the line and release relays 351 and 352 deenergize. Relay 354 also deenergizes, upon the deenergization of release relay 352. As a result of the line conductors 25 and 27 being extended through to the secondary switches SS⁹, the said switch SS⁹ operates to select an idle trunk in the usual manner, which trunk it will be assumed is the one extending to the repeater R². That being the case, the associated selector (not shown) in South is prepared for operation in the usual manner.

In response to the calling of the four digits in the desired number, the thousands selector in South to which the connection has been extended, a hundreds selector, and a connector are operated in the usual manner to extend the connection to the desired line.

Call from Lincoln to Upland.

In order to explain the operation of the digit absorbing repeaters DAR-DAR², inclusive, Fig. 11, of which the digit absorbing repeater DAR² is shown by means of the usual circuit diagrams in Fig. 5, it will be assumed that the subscriber at substation A desires to converse with a subscriber whose line terminates in Upland, which office is reached by way of Medbury, Fig. 10. When the receiver is removed at substation A, the line switch C operates in the hereinbefore described manner to pick out an idle first selector, which selector it will be assumed is the selector D.

In response to the calling of the first letter U in the desired number, the selector D raises its wipers to the eighth level (not shown in Fig. 1) and selects an idle secondary switch, the secondary switch SS⁴, Fig. 11, for example. Upon being seized, the secondary switch SS⁴ operates to select an idle repeater, the repeater R', Figs. 4 and 11, for example. Upon the repeater R' being seized, the distant selector E' in Medbury, associated therewith, is prepared for operation in the usual manner.

In response to the calling of the second letter P in the desired number, the selector E' raises its wipers to the sixth level and selects an idle secondary switch, the secondary switch SS¹⁰ for example, which switch, upon being seized, selects an idle digit-absorbing repeater, the digit-absorbing repeater DAR² for example. Upon the repeater DAR² being seized, line relay 240, upon energizing, closes a bridge across the associated trunk conductors 252 and 253 at armature 245, whereupon the associated incoming selector in Upland (not shown) is prepared for operation in the usual manner. As a further result of the energization of line relay 240, it closes at armature 244 a circuit for release relay 241, a branch of this circuit extends by way of the resting contact of armature 250 and said armature to

relay 242. Relay 242, upon energizing, places a shunt around armature 245 and its working contact of line relay 241 at armature 249, and at armature 248 prepares a locking circuit for itself. Release relay 241, upon energizing, prepares an energizing circuit for relay 243 and a locking circuit for relay 242 at armature 247, and at armature 246 places ground upon the associated release trunk conductor, thereby establishing the usual holding circuit for the secondary switch SS¹⁰ and the selector E'.

In response to the calling of the third letter L in the desired number, five interruptions are produced in the circuit of line relay 240 of the repeater DAR². Upon deenergizing in response to each of these interruptions, line relay 240 separates armature 245 from its working contact, but this does not open the bridge across the conductors 252 and 253 owing to the fact that armature 245 and its working contact are shunted by armature 249 and its working contact. Line relay 240, upon deenergizing in response to the first interruption produced in its circuit, closes at armature 244 and its resting contact a circuit for relay 243, by way of armature 247 and its working contact and the normally closed contacts controlled by armature 251. Relay 243, upon energizing, locks itself to the release trunk conductor and opens its initial circuit at armature 251, and at armature 250 shifts the circuit of relay 242 from the working contact of armature 244 to the resting contact thereof. Slow acting relay 242 now receives an impulse of current upon each deenergization of line relay 240 over the following circuit: From ground by way of armature 244 and its resting contact, armature 247 and its working contact, working contact of armature 248 and said armature, working contact of armature 250 and said armature, and relay 242 to battery. Relay 242, being slow acting, retains its armature attracted throughout the series of interruptions. At the end of the series of interruptions, line relay 240 comes to rest in an energized condition, leaving the circuit of relay 242 open. Relay 242, upon deenergizing, opens a further point in its circuit at armature 248, and at armature 249 removes the shunt from around armature 245 and its working contact. It is very obvious that the calling of the third letter in the office name has not produced any effect in the distant selector associated with the repeater DAR² for the reason that the bridge across conductors 252 and 253 was maintained closed throughout the entire series of interruptions.

In response to the calling of the four digits in the desired number, the four series of interruptions produced in the circuit of line relay 240 are repeated in the usual man-

ner at armature 245 over the associated trunk comprising conductors 252 and 253 to the switches in Upland. As a result the thousands selector associated with the repeater 5 DAR², a hundreds selector, and a connector are operated in the well-known manner to extend the connection to the desired line.

Call from Lincoln to Pontiac.

10 It has been shown in an example given hereinbefore how the traffic separator TS, Fig. 7, sends the traffic by way of the secondary switch SS²⁴ when the associated bi-level repeater BLR, Fig. 6, is seized by way 15 of the path which is accessible to the secondary switch SS¹⁷, Fig. 6, and in order to show how the said traffic separator TS sends the traffic out by way of the secondary switch SS²⁶ when the bi-level repeater BLR is seized by way of the path accessible to the secondary switch SS⁸, it will be assumed 20 that the subscriber at substation A desires to converse with a subscriber whose line terminates in Pontiac. When the receiver is 25 removed at substation A, an idle first selector, the selector D for example is picked out in the usual manner by the line switch C.

In response to the calling of the first letter P in the desired number, the selector D 30 raises its wipers to the sixth level and selects an idle universal switcher, the universal switcher US for example, Fig. 11. When this occurs, the connection is extended by way of the secondary switch SS³ and a repeater, the repeater R for example, to Dunham, in addition to being extended by way 35 of the secondary switch SS⁶ and a repeater, the repeater R' for example, to Medbury. These two paths are taken for the reason 40 that the first two letters N and O of North conflict with the first two letters P and O of Pontiac, N and P both appearing in the sixth hole of the calling device, Fig. 9.

In response to the calling of the second 45 letter O in the desired number, the selector E' in Medbury raises its wipers to the tenth level and selects an idle trunk, the trunk extending to the selector F' for example. At the same time the selector E in Dunham 50 raises its wipers to the tenth level and, through a secondary switch, such as the secondary switch SS¹², selects an idle trunk to North by way of a digit-absorbing repeater, the digit-absorbing repeater DAR for example.

In response to the calling of the third letter N in the desired number, the circuit of the line relay of the digit-absorbing repeater DAR in Dunham, Fig. 11, is interrupted in 60 the usual manner, but the interruptions are not repeated to the associated selector in North, but are absorbed in the same manner as the first character called after the digit-absorbing repeater DAR² is seized, as explained hereinbefore.

In Medbury, in response to the calling of the third letter N in the desired number, the selector F', Fig. 5, raises its wipers to the sixth level and selects an idle trunk, the trunk extending to the secondary switch 70 SS¹⁸ for example. That being the case, the secondary switch SS¹⁸ operates in the usual manner to select an idle bi-level repeater, the bi-level repeater BLR for example. It will be noted that when the repeater BLR is seized over this path conductor 283 is not connected up and consequently a preliminary ground impulse is not sent out over trunk conductor 277. In response to the seizure of the repeater BLR, line relay 270, 75 upon energizing, closes a point in the bridge to be subsequently closed across the conductors 277 and 278 at armature 274, and at armature 273 closes the circuit of release relay 271. Release relay 271, upon energizing, 80 places ground upon the associated release trunk conductor at armature 276, thereby establishing the usual holding circuit for selectors E' and F' and the secondary switch SS¹⁸, and at armature 275 closes a 85 circuit for relay 272. Relay 272, upon energizing, disconnects trunk conductor 277 from discriminating conductor 283 and completes the bridge across conductors 277 and 278. 90

In the traffic separator TS, relays 401 and 402 now energize in series over conductors 277 and 278, thereby closing a circuit for switching relay 404 by way of armature 405 and its working contact and armature 406 100 and its working contact. Switching relay 404, upon energizing, disconnects relay 401 from conductor 277 at armature 411; disconnects relay 402 at armature 412; and at armatures 410 and 412 and their 105 working contacts extends conductors 277 and 278 through to the line conductors of the secondary switch SS²⁵. The secondary switch SS²⁵ now operates in the usual manner to select an idle trunk, the trunk extending to the selector G³ for example. 110

In the universal switcher US, which switcher is similar to the universal switcher US', Fig. 1, with the exception that the universal switcher US does not have a third 115 outgoing path corresponding to the lower path of the universal switcher US', which is the path leading out by way of the secondary switch SS²⁶, the recording device therein, having recorded the second and third letters dialled, causes the connection extending to Medbury to be definitely chosen and the connection to Dunham by way of the secondary switch SS³ to be released in the usual manner. 120

In response to the calling of the four digits in the desired number, the selector G³, Fig. 7, a hundreds selector, and a connector are operated in the usual manner to extend the connection to the desired line. 130

The various features of the invention, having been described and ascertained in the foregoing, will now be pointed out in the appended claims.

5. What is claimed is:

1. In a telephone system, a switching device having a wiper associated therewith, a bank of contacts accessible to said wiper, a plurality of relays, each of a plurality of 10 said contacts being connected to one of said relays, means responsive to impulses representing part of a telephone number for energizing one of said relays by moving said wiper into engagement with the bank contact 15 associated therewith, a cut off relay, means for energizing said cut off relay whenever any one of the first mentioned relays is energized, and means controlled by said cut off relay for disconnecting each of 20 said first mentioned relays from its associated bank contact.

2. In a telephone system, a switching device having a wiper associated therewith, a bank of contacts accessible to said wiper, 25 a plurality of relays, each of a plurality of said contacts being connected to one of said relays, means responsive to impulses representing part of a telephone number for energizing one of said relays by moving said 30 wiper into engagement with the bank contact associated therewith, a cut off relay, means for energizing said cut off relay in series with any one of the first mentioned relays, and means controlled by said cut off 35 relay for disconnecting each of said first mentioned relays from its associated bank contact.

3. In a telephone system, a switching device, two paths outgoing from said device, 40 means responsive to the seizure of said device for extending a connection therefrom by way of the first of said paths, means responsive to a train of impulses representing part of a called number for further extending 45 the connection over said first path and for releasing the connection established over said first path at the end of said train of impulses, and means responsive to the following train of impulses for connecting up 50 the second of said paths to said device at the end of said following train of impulses.

4. In a telephone system, a trunk terminating at one end in an automatic repeater and at the other in an automatic step by 55 step switch, means for seizing said repeater and for subsequently sending a train of switch operating impulses to it, means responsive to said train of impulses for preparing said repeater to repeat the following 60 train of impulses to said automatic switch, and means at said repeater for repeating said following train of impulses over said trunk to said automatic switch.

5. In a telephone system, an automatic repeater, an inter-office trunk extending there-

from, means responsive to the seizure of said repeater for closing a switch control circuit over said trunk and for subsequently repeating impulses over said trunk, means for sending a plurality of trains of impulses 70 to said repeater, and means for preventing the said repeater from repeating the first of said trains of impulses over said trunk.

6. In a telephone system, a trunk, a traffic separator, said trunk terminating at the distant end in said separator, two paths outgoing from said separator, two relays associated with said trunk, means responsive to the seizure of said trunk under one condition for energizing one of said relays alone, 75 means responsive to the seizure of said trunk under another condition for energizing both of said relays, means responsive to the first mentioned energization for connecting said trunk to one of said paths, and means responsive to the second named energization for connecting said trunk to the other of said paths.

7. In a telephone system, a trunk, two seizing paths leading to said trunk, two paths outgoing from the distant end of said trunk, two relays associated with said distant end, means responsive to the seizure of said trunk by way of one of said seizing paths for energizing one of said relays alone, 80 means responsive to the seizure of said trunk by way of the other of said seizing paths for energizing both of said relays, means responsive to the first mentioned energization for connecting said trunk with one of said outgoing paths, and means responsive to the last mentioned energization for connecting said trunk to the other of said outgoing paths.

8. In a telephone system, a trunk line, an automatic repeater associated with said trunk line, a relay for said repeater, means for seizing said trunk line via said repeater and for transmitting a plurality of trains of impulses to said repeater, means responsive to said seizure for energizing said relay to prevent the repeater from repeating the received impulses to said trunk line, and means responsive to the first train of impulses for deenergizing said relay to permit the following train of impulses to be repeated to said trunk.

9. In a telephone system, a trunk line, a repeater having a line relay and a slow acting relay, a circuit for said slow acting relay closed by said line relay upon energizing, means for producing two series of deenergizations of said line relay, means responsive to the first deenergization of the first series for shifting the circuit of said slow acting relay so that it is closed only upon a deenergization of said line relay, whereby said slow acting relay remains operated until the end of the first series of deenergizations and falls back at the end of such 125 130

series, and means controlled by said slow acting relay upon falling back for placing said trunk line in condition to be opened upon each deenergization of the second series of deenergizations of said line relay.

10. In a telephone system, a trunk line, a repeater having a line relay energized responsive to a seizure of said repeater, contacts closed responsive to the energization of said line relay to close a control bridge across said trunk line, other means controlled by said line relay to close a shunt around said contacts, means for producing two series of deenergizations of said line relay, and means responsive to the first series of deenergizations of said relay for removing said shunt from around said contacts to permit said bridge to be opened upon each deenergization of said second 20 series.

11. In a telephone system, a trunk line in two sections, a line relay responsive to series of impulses received over the first section for repeating impulses into said second section, 25 a second relay controlled by said line relay for rendering the same ineffective to repeat the first series of impulses received, and means for causing the deenergization of said second relay at the end of the first series 30 of impulses.

12. In a telephone system, a trunk line in two sections, a repeater at the junction of said sections, a line relay in said repeater responsive to series of impulses received over 35 the first section for repeating such impulses over the second section, and means in said repeater for absorbing the first series of impulses received by preventing the line relay from repeating them.

40 13. In a telephone system, a trunk line in two sections, a repeater at the junction of said sections, a line relay in said repeater responsive to series of impulses received over the first section for repeating such impulses over the second section, means in said repeater for absorbing the first series of impulses received by preventing them from being repeated, and means responsive to the first impulse of the first series for rendering said absorbing means ineffective at 45 the end of the first series of impulses.

14. In a repeater, a line relay, repeating contacts on said line relay, a second relay for shunting said contacts, and two circuits 55 for said second relay controlled by said line relay on energization and deenergization, respectively.

60 15. In a repeater, a line relay, repeating contacts on said line relay, a second relay for shunting said contacts, an initial energizing circuit for said second relay closed by the energization of said line relay, a holding circuit for said second relay closed upon the deenergization of said line relay, 65 and a third relay for shifting said second

relay from said first circuit to the second.

16. In a telephone system, a trunk line in two normally disconnected sections, means individual to said trunk line for registering series of impulses received over 70 the first section, a relay for connecting said sections, means for energizing said relay responsive to the registration of the first series only if the first series has a particular value, and means for energizing said relay responsive to the registration of the second series if the first series has a different value.

17. In a telephone system, a trunk line in two normally disconnected sections, means including a single-digit switch for registering two successive series of impulses received over the first section by operating, releasing and reoperating, a relay for connecting said sections, and means for energizing said relay responsive to the registration of either 80 the first or the second of said series of impulses depending on the value of the said first series.

18. In a telephone system, a trunk line in two normally disconnected sections, means 90 for registering series of impulses received over the first section, a relay for connecting said sections, means for energizing said relay responsive to the registration of a single series of impulses of a particular 95 value, and means for energizing said relay responsive to the registration of two like series of impulses differing in value from the first mentioned series.

19. In a telephone system, a trunk line 100 having two branches, means for transmitting series of impulses over said trunk line, means for repeating the first series of impulses over one of said branches, means for absorbing the next series, and means for directing the next series over the other branch.

20. In a telephone system, a trunk line having two branches, means for transmitting series of impulses over said trunk line, means for registering the first two series of impulses received and for repeating the first series over one of said branches, means for preventing the repeating of the second series if the first is of a particular value, and means responsive to the registration of the 115 second series for connecting the other of said branches to said trunk line.

21. In a telephone system, a trunk line accessible over two paths, means responsive to a seizure of said trunk over either path 120 for placing a switch control bridge across said trunk line, two branches outgoing from said trunk line at the distant end, connecting means responsive to the closure of said bridge for connecting said trunk line to the first of said branches, and means responsive to a seizure of said trunk line over one of said paths for closing a control circuit over one trunk conductor only prior to the closing of said bridge to switch said 125 130

- trunk to the other of said outgoing paths.
22. In a telephone system, a trunk line accessible to two automatic switches, two outgoing branches at the distant end of said trunk line, means controlled by the first of said switches to select the first of said outgoing branches, and means in the second of said switches for selectively controlling the selection of the second of said branches.
- 10 23. The combination in a telephone system, of a trunk line having two distant outgoing branches and an automatic switch for seizing said trunk line at the incoming end, with means in said switch for selecting a particuuar one of said branches.
- 15 24. In a telephone system, a line, a second line, means for connecting the two together, means individual to the first line for closing a signal circuit over the second line upon said connection being made, and means individual to the second line for opening said circuit at the end of a predetermined time interval to terminate the signal.
- 20 25. In a telephone system, a line branched at the incoming end, corresponding branches at the outgoing end, means including a switch for seizing one incoming branch and for closing a circuit over said line including said switch, means at the outgoing end responsive to the closure of said circuit to select the outgoing branch corresponding to the seized incoming branch, and means individual to said line at the incoming end thereof for opening said circuit when it is no longer needed.
- 25 26. In a telephone system, a line branched at one end, means including a switch for making connection with said line at the other end and for closing a circuit over said line including said switch, means at the said branched end of said line responsive to the closure of said circuit for selecting a particular branch, and means individual to said line at the other end for opening said circuit when it is no longer needed.
- 30 27. In a telephone system, a trunk, means for transmitting groups of digit impulses over said trunk, a device associated with the talking conductors of the trunk for absorbing a group of impulses, and means operated responsive to the cessation of the impulses of said group to electrically disassociate said device from the talking conductors provided the absorbed group comprises a certain number of impulses.
- 35 28. In a telephone system, a line, means for sending groups of impulses over said line, each group representing a digit, a digit absorber, a switch for extending the talking conductors of said line to the digit absorber, and means within the digit absorber to absorb one of the groups of impulses and to electrically disassociate itself from the talking conductors of the line responsive to the cessation of the impulses of that group, said disassociation being effected or not depending upon the number of impulses in the absorbed group.
- 40 29. In a telephone system, a line, means for sending groups of impulses over said line, each group representing a digit, a digit absorber including a device for counting said impulses, a switch for extending the talking conductors of said line to the digit absorber, another switch, and means within the digit absorber and including said counting device to absorb one of the groups of impulses, to electrically disassociate itself from the talking conductors of the line responsive to the cessation of the impulses of that group, and to connect the talking conductors to said other switch.
- 45 30. In a telephone system, a line, means for sending a plurality of groups of impulses over said line, means for absorbing one of said groups of impulses, a switching device responsive to a subsequent group of impulses, and means responsive to said absorption for extending the said line to said device only in case the absorbed group contains a predetermined number of impulses.
- 50 31. In a telephone system in which calls are progressed step by step under the control of current impulses representing digits, means for fully determining the next progression step upon the receipt of a given digit, means for subsequently receiving and absorbing a digit not indicating a further progression, and means for performing the said predetermined progression step upon the completion of said absorption.
- 55 In witness whereof, I hereunto subscribe my name this 24th day of April, A. D. 1922.
- ARTHUR BESSEY SMITH.
